CONTROL CONSOLES FOR CYCLICALLY OPERATIVE APPLIANCES, SUCH AS CLOTHES WASHING MACHINES

Charles H. Schmitt, Lake Forest, Ill., assignor to General Electric Company, a corporation of New York
Filed Dec. 16, 1963, Ser. No. 330,991
23 Claims. (C.I. 68—12)

The present invention relates to control consoles for cyclically operative appliances, such as clothes washing machines, and to such appliances incorporating such control consoles.

It is a general object of the invention to provide a control console for a cyclically operative appliance that incorporates facility for preselecting a number of cycle components for inclusion in a program to be carried out in the appliance, facility for recommending particular cycle components to be preselected for inclusion in a given number of programs to be carried out in the appliance, facility for producing a visual indication of the ones of the preselected cycle components that conform to those recommended and of the others of the preselected cycle components that nonconform to those recommended, and facility for initiating operation of the appliance to carry out a program including the preselected cycle components, whereby the control console gives the operator complete freedom of choice in the preselection of cycle components to be included in a program to be carried out in the appliance, but prompts or informs the operator with respect to whether the preselected cycle components conform or nonconform to those recommended.

Another object of the invention is to provide a control console of the character described, wherein the facility for preselecting the cycle components essentially comprises a plurality of manually operable two-position devices respectively corresponding to the different cycle components, wherein the two positions of each one of the devices respectively correspond to the inclusion and to the exclusion of the corresponding one of the cycle components.

Another object of the invention is to provide a control console of the character described, wherein the facility for recommending particular cycle components to be preselected for inclusion in the number of programs to be carried out in the appliance is selectively presettable in terms of a corresponding number of different types of materials that may be processed in the appliance, so that the cycle components recommended to be preselected for inclusion in a given program are correlated with respect to the corresponding type of material to be processed in the appliance.

Another object of the invention is to provide a control console of the character described, wherein the facility for producing the visual indication of the ones of the preselected cycle components that conform to those recommended and of the others of the preselected cycle components that nonconform to those recommended are correlated with the individual positions of the corresponding ones of the devices, so that the operator may readily operate the devices to match the preselected cycle components and the recommended cycle components, if such is considered to be desirable.

Another object of the invention is to provide a control console of the character described, wherein the facility for preselecting the cycle components and the facility recommending the particular cycle components and the facility for producing the visual indication comprise a unitary mechanism including common control elements.

Another object of the invention is to provide a control console of the character described, wherein the facility for producing the visual indication is of the color-key

2

type so that light beams of one color are transmitted to the ones of the devices corresponding to the matching between the preselected and the recommended cycle components and so that light beams of another color are transmitted to the others of the devices corresponding to the mismatching between the preselected and the recommended cycle components.

Another object of the invention is to provide a control console of the character described, wherein the facility for preselecting the cycle components includes a plurality of two-position snap-acting switches each provided with a manually operable actuating number of the rocking type, the facility for recommending the cycle components includes a rotatably mounted tube upon which the actuating members are rockably mounted in side-by-side relation, and the facility for producing the visual indication includes an elongated lamp disposed in the tube and groups of coordinate windows arranged in the tube and respectively cooperating with the actuating members rockably mounted thereupon.

A further object of the invention is to provide a cyclically operative appliance incorporating a control console of the character described, wherein the operative elements of the control console are coordinated with respect to the cycle components of the appliance, whereby an operator may readily preselect and selectively control the programs for the appliance in accordance with the types of materials that may be processed in the appliance.

A still further object of the invention is to provide in an automatic clothes washing machine, a control console of the character described.

Further features of the invention pertain to the particular arrangement of the elements of the control console and of the cyclically operative appliance incorporating the control console, whereby the above-outlined and additional operating features thereof are attained.

The invention, both as to its organization and method of operation, together with further objects and advantages thereof, will best be understood by reference to the following specification, taken in connection with the accompanying drawings, in which:

FIGURE 1 is a combined schematic illustration and skeleton front view of a cyclically operative appliance, in the form of an automatic clothes washing machine, incorporating a control console, and an electric control circuit, and embodying the present invention;

FIG. 2 is an enlarged front view of a manually operable dial forming a part of a program controller incorporated in the control console provided in the clothes washing machine of FIG. 1;

FIGS. 3, 4 and 5, taken together and arranged in sequence from left to right, are a diagram of the electric control circuit incorporated in the machine;

FIG. 6 is a time-sequence control chart of the control cams carried by the operating shaft of the program controller incorporated in the electric control circuit, as illustrated in FIG. 5;

FIG. 7 is a somewhat enlarged front view of the upper portion of the clothes washing machine, as shown in FIG. 1;

FIG. 8 is an enlarged front view of the control console that is incorporated in the backsplash of the clothes washing machine, as shown in FIG. 7;

FIG. 9 is an enlarged fragmentary front perspective view of one of the manually operable switch-actuating members incorporated in the control console and indicating the manner in which the same is mounted for rocking movements between its two operating positions;

FIG. 10 is an enlarged end elevational view of the actuating member of FIG. 9, illustrating the same in one of its operating positions;

FIG. 11 is an enlarged end elevational view of the

actuating member of FIG. 9, illustrating the same in the other of its operating positions;

FIG. 12 is an enlarged front view, partly broken away, of the left-hand side of the control console, as illustrated in FIG. 8;

FIG. 13 is an enlarged horizontal sectional view of the left-hand side of the control console, this view being taken in the direction of the arrows along the line 13—13 in FIG. 12;

FIG. 14 is an enlarged plan view of a chart and control sheet that is incorporated in the glass tube upon which the actuating members are rockably mounted, as shown in FIG. 12;

FIG. 15 is a chart of the clothes processing programs that are recommended for the several types of fabrics indicated; and

FIG. 16 is a chart of the operating positions of the actuating members in the control console required to preset the recommended clothes processing programs, as set forth in the chart of FIG. 15.

Referring now to FIG. 1 of the drawings, the clothes washing machine 10 there illustrated is of the spin-tub type and of the general construction and arrangement of that disclosed in U.S. Patent No. 2,639,618, granted on May 26, 1953 to Jacob W. McNairy. More particularly, the machine 10 comprises a substantially square supporting base 11 carrying wall structure defining an upstanding casing 12 including a substantially horizontally disposed top wall 13 having a top opening therein provided with a cooperating top door 14 arranged for movements between open and closed positions with respect thereto. Housed within the casing 12 is an upstanding drain tub 15 that is suitably supported upon the base 11 and provided with an open top that is sealed against the underside of the top wall 13 in surrounding relation with respect to the top opening therein. A unitary mechanism 16 is arranged in upstanding position in the lower portion of the casing 12 and suitably supported upon the base 11 by structure indicated at 17. The mechanism 16 includes a casing 18 that is arranged in an opening provided in the bottom wall of the drain tub 15 and sealed in place, whereby the lower portion of the casing 18 is disposed below the bottom wall of the drain tub 15 and the upper portion of the casing 18 is disposed above the bottom wall of the drain tub 15. The casing 18 houses in the lower portion thereof an electric drive motor 40 of the two-speed reversible-rotor type that is also of the 4-pole, 6-pole, split-phase, induction type, as described more fully hereinafter; the rotor of which drive motor 40 is operatively connected to a water pump, not shown, that is also housed within the casing 18. In the arrangement the pump mentioned is provided with an inlet to which there is connected an inlet conduit 15a communicating with the bottom of the drain tub 15, and also an outlet to which there is connected an outlet conduit 15b extending to drain plumbing, not shown. In the arrangement, rotation of the rotor of the drive motor 40 in at least the reverse direction thereof operates the pump mentioned, so that any water in the drain tub 15 is pumped therefrom to the drain plumbing via the conduits 15a and 15b in an obvious manner.

Also, the unitary mechanism 16 comprises an outer rotatable element 19 arranged adjacent to the upper end of the casing 18 and disposed exteriorly thereof and positioned in the lower portion of the drain tub 15; which rotatable element 19 carries an upstanding spin tub 20 that is of conventional construction provided with a substantially annular wall that is upwardly and outwardly flared and having an open top disposed somewhat below the top opening provided in the top wall 13 and in alignment therewith, thereby to accommodate ready placement and removal of the clothes with respect to the spin tub 20 through the top opening mentioned, when the top door 14 occupies its open position. Further, the mechanism 16 comprises an inner oscillatable element 21 projecting

through the extreme upper end of the rotatable element 19 and carrying an upstanding agitator 22 arranged substantially centrally within the spin tub 20. Moreover, the upper open end of the spin tub 20 carries the usual balance ring 23 through which an annular array of openings 23a are arranged for the centrifugal discharge of the water therethrough from the spin tub 20 into the drain tub 15.

Finally, the unitary mechanism 16 comprises operative mechanism for selectively interconnecting the rotor of the drive motor respectively to the agitator 22 and to the spin tub 20. In the arrangement, when the rotor of the drive motor 40 is rotated in the forward direction, the agitator 22 is oscillated thereby, and when the rotor of the drive motor 40 is rotated in the reverse direction, the spin tub 20 is rotated thereby. Of course, oscillation of the agitator 22 effects a washing action upon the clothes suspended in the wash water contained in the spin tub 20, while rotation of the spin tub 20 effects a water-extraction action upon the clothes contained in the spin tub 20. Specifically, rotation of the spin tub 20 causes the wash water contained therein to be flung therefrom by centrifugal force and then causes water absorbed by the clothes to be extracted therefrom by centrifugal action and flung from the spin tub 20. The water flung from the spin tub 20 is caught by the drain tub 15, whereby it is pumped to the drain plumbing, not shown, by the operating pump previously mentioned that is housed within the casing 18 of the mechanism 16. Thus, the washing and water-extracting actions may be selectively effected upon the clothes contained in the spin tub 20 by selectively controlling the drive motor 40 in order to cause rotation of the rotor thereof in the respective forward and reverse directions, as required.

Further, the machine 10 comprises a water supply system indicated schematically as including a hot water supply pipe 24 and a cold water supply pipe 25, as well as a delivery tube 26 directly communicating with the open top of the spin tub 20. Also, a valve 27 is arranged in the hot water supply pipe 24 and a valve 28 is arranged in the cold water supply pipe 25. The valves 27 and 28 are of the solenoid-operated type, the solenoids thereof being respectively indicated at 27a and 28a; and the valves 27 and 28 are biased into their closed positions. When the solenoid 27a is energized, the valve 27 is operated into its open position so that hot water is supplied from the hot water supply pipe 24 via the tube 26 into the spin tub 20; and when the solenoid 28a is energized, the valve 28 is operated into its open position so that cold water is supplied from the cold water supply pipe 25 via the tube 26 into the spin tub 20. Of course, the conjoint operations of the valves 27 and 28 into their open positions bring about the supply of warm water via the tube 26 into the spin tub 20, as a consequence of the mixing of the hot water from the hot water supply pipe 24 and the cold water from the cold water supply pipe 25.

Further, the machine 10 comprises a detergent dispenser 30 and a bleach dispenser 35. The detergent dispenser 30 is of the solenoid-operated type, the solenoid of which is indicated at 30a, and is provided with a delivery tube 31 directly communicating with the open top of the spin tub 20. Likewise, the bleach dispenser 35 is of the solenoid-operated type, the solenoid of which is indicated at 35a, and is provided with a delivery tube 36 directly communicating with the open top of the spin tub 20. The dispenser 30 is adapted to contain a suitable liquid detergent and is operative in response to energization-deenergization of the solenoid 30a to effect the delivery of a measured volume or charge of the liquid detergent therefrom via the tube 31 into the spin tub 20. Likewise, the dispenser 35 is adapted to contain a suitable liquid bleach and is operative in response to energization-deenergization of the solenoid 35a to effect the delivery of a measured volume or charge of the liquid bleach therefrom via the tube 36 into the spin tub 20.

In the machine 10, the valves 27 and 28, as well as the dispensers 30 and 35, are suitably housed in the casing 12; and preferably, the dispensers 30 and 35 are provided with respective fill conduits, not shown, that are accessible through the top opening provided in the top wall 13, when the top door 14 occupies its open position, so as to accommodate the ready filling thereof with the required liquids mentioned. Of course, it will be understood that in FIG. 1, the showings of the water supply system and the dispensers 30 and 35 are entirely diagrammatic and that actually these elements of the machine 10 are housed within the casing 12, as previously noted.

Referring to FIG. 5, it will be observed that the drive motor 40 of the 4-pole, 6-pole, split-phase, induction type includes a reversible rotor 41 and a cooperating frame carrying a 4-pole run winding 42, a 6-pole run winding 43 and a 4-pole start winding 44. The rotor 41 is carried by an operating shaft 45 to which there is connected a speed-responsive device 46 of the fly-ball governor type that includes a movable shaft 47 carrying two contact bridging members 48 and 49. Each of the contact bridging members 48 and 49 is provided with both front and rear contact sets governed thereby.

When the 4-pole run winding 42 is energized with forward polarity, the rotor 44 runs in the forward direction at its high speed of approximately 1725 r.p.m. effecting normal oscillation of the agitator 22 at a rate of about 64 cycles per minute that is suitable for washing normal fabrics; and when the 6-pole run winding 43 is energized with forward polarity, the rotor 44 runs in the forward direction at its low speed of approximately 1140 r.p.m. effecting gentle oscillation of the agitator 22 at a rate of about 45 cycles per minute that is suitable for washing delicate fabrics. When the 4-pole run winding 42 is energized with reverse polarity, the rotor 44 runs in the reverse direction at its high speed of approximately 1725 r.p.m. effecting normal spinning of the spin tub 20 at a speed of about 640 r.p.m. that is suitable for water-extracting normal fabrics; and when the 6-pole run winding 43 is energized with reverse polarity, the rotor 44 runs in the reverse direction at its low speed of approximately 1140 r.p.m. effecting gentle spinning of the spin tub 20 at a speed of about 420 r.p.m. that is suitable for water-extracting delicate fabrics.

Referring now to FIGS. 1, 7 and 8, the rear portion of the top wall 13 carries an upstanding backsplash 29 that, in turn, carries a control console 100 embodying the features of the present invention. More particularly, the control console 100 is arranged in a window 29a provided in the front wall of the backsplash 29 and carries manually operable control facility, including, as best shown in FIG. 3, a number of washes switch 110, a first wash temperature switch 120, a soak control switch 130, an agitate control switch 140, a number of rinses switch 150, a rinses temperature switch 160, and a spin control switch 170; which switches are of the two-position snap-acting type, and respectively provided with the corresponding switch-actuating members 110R, 120R, 130R, 140R, 150R, 160R and 170R. Also, each of these switches is of the toggle-operated type; whereby the actuating members 110R, 120R, etc., are arranged in side-by-side relation and mounted for independent rocking movements between the two operating positions thereof, as more fully explained hereinafter. Specifically, as shown in FIG. 8, the control console 100 comprises a front plate 101 having a window 102 therein in which the actuating members 110R, 120R, etc., are mounted. Also, the actuating members 110R, 120R, 130R, 140R, 150R, 160R and 170R respectively comprise pairs of operating lugs or tabs 111, 112 and 121, 122 and 131, 132 and 141, 142 and 151, 152 and 161, 162 and 171, 172, so as to facilitate the rocking movements thereof, as previously noted. Also, this manually operable control facility includes, as best shown in FIG. 4, a fill control switch 180 and a time control switch 190; which switches 75

are of the 3-position rotary type respectively provided with manually operable wheels or dials 182 and 192 respectively projecting through two windows 103 and 104 formed in the front plate 101. Further, this control facility includes, as best shown in FIG. 5, a program controller 50 provided with a rotatably mounted operating shaft 51 projecting through a hole formed in the front plate 101 and carrying a control dial 52 on the outer end thereof, the control dial 52 being positioned immediately forwardly of the front plate 101 and co-operating with an associated index plate 53 carried by the front plate 101. On the front plate 101, the control dial 52 may be arranged intermediate the windows 103 and 104.

As explained more fully hereinafter in conjunction with FIGS. 9, 10 and 11, the actuating members 110R, 120R, etc., are mounted for rocking movements upon a glass tube 301, that is, in turn, mounted for rotation upon the rear side of the front plate 101. The extreme left-hand end of the tube 301 carries a manually operable wheel 302 rigidly secured thereto and projecting through a window 105 formed in the front wall 101, the window 105 being arranged adjacent to the left-hand end of the front wall 101. Further an index plate 303 is carried by the tube 301 adjacent to the left-hand end thereof; which index plate 303 is visible through a window 106 formed in the front wall 101.

As best shown in FIG. 3, the switches 110, 120, etc., are of conventional construction and are selectively operated between the two positions thereof by the corresponding ones of the actuating members 110R, 120R etc. In the switch 110, the tabs 111 and 112 respectively comprise a one-wash tab and a two-wash tab; and the actuator 110R governs three switch springs 113, 114 and 115. In the switch 120, the individual tabs 121 and 122 respectively comprise a hot tab and a warm tab; and the actuator 120R governs a switch spring 123. In the switch 130, the individual tabs 131 and 132 respectively comprise a soak tab and an agitate tab; and the actuator 130R governs a switch spring 133. In the switch 140, the individual tabs 141 and 142 respectively comprise a normal tab and a gentle tab; and the actuator 140R governs two switch springs 143 and 144. In the switch 150, the individual tabs 151 and 152 respectively comprise a one-rinse tab and a two-rinse tab; and the actuator 150R governs two switch springs 153 and 154. In the switch 160, the individual tabs 161 and 162 respectively comprise a warm tab and a cold tab, and the actuator 160R governs a switch spring 163. In the switch 170, the individual tabs 171 and 172 respectively comprise a normal tab and a gentle tab; and the actuator 170R governs two switch springs 173 and 174.

As shown in FIG. 4, the fill control switch 180 is of the manually operable rotary type including a rotatably mounted operating shaft 181 carrying a manual dial and index 182 on the outer end thereof and a wiper 183 on the inner end thereof. The index 182 cooperates with an index pointer carried on the front wall 101 of the control console 100, and the wiper 183 cooperates with three contact segments 184, 185 and 186. When the index "Large Load" cooperates with the marker, the wiper 183 engages only the contact segment 184; when the index "Normal Load" cooperates with the marker, the wiper 183 engages the two contact segments 184 and 185; and when the index "Small Load" cooperates with the marker, the wiper 183 engages the two contact segments 184 and 186. The time control switch 190 is of the manually operable rotary type including a rotatably mounted operating shaft 191 carrying a manual dial and index 192 on the outer end thereof and a wiper 193 on the inner end thereof. The index 192 cooperates with an index pointer carried on the front wall 101 of the control console 100, and the wiper 193 cooperates with three contact segments 194, 195 and 196. When the index "10 minutes" cooperates with the marker, the wiper 193 engages only the contact segment

194; when the index "7 minutes" cooperates with the marker, the wiper 193 engages the two contact segments 194 and 195; and when the index "4 minutes" cooperates with the marker, the wiper 193 engages the three contact segments 194, 195 and 196. Also, for a purpose more fully explained hereinafter, the legends "10," "7" and "4" are respectively provided with backgrounds that are red, yellow and blue in color.

As best shown in FIG. 5, the program controller 50 further comprises a plurality of insulating cams 7B, 6B, 1B, 3B, 5B, 2B, 6T, 4T, 1T, 4B, 5T, 3T and 2T, that are rigidly secured to the operating shaft 51, and that respectively control the armature springs C1, MC, C2, FL, F2, MP, S2, S4, P5, P2, P3, P4 and P6. The armature springs C1, MC, FL, F2, MP, S2, S4, P2, P3, P4 and P6 respectively govern the pairs of switch springs CW, HR and H, PR and PF, ML and BD, NF and W, S and K1, J1 and K2, J2 and A1, A2 and A3, B1 and A4, B2 and BP, E; while the armature springs C2 and P5 respectively govern the single switch springs CR and SS.

Also, the operating shaft 51 is mounted for longitudinal axial movement, as well as for the rotary movement previously described; whereby the operating shaft 51 carries a contact bridging member 60 that is adapted selectively to bridge an associated pair of front contacts and constituting a line switch. More particularly, when the manual dial 52 is depressed, moved inwardly toward the front wall 101, the operating shaft 51 is moved longitudinally inwardly so as to actuate the line switch 60 into its open position; conversely, when the manual dial 52 is withdrawn, pulled outwardly away from the front wall 101, the operating shaft 51 is moved longitudinally outwardly so as to actuate the line switch 60 into its closed position.

Also, the program controller 50 comprises a shaft 54 that is mounted only for rotary movement; and the outer end of the shaft 54 is connected to the adjacent inner end of the operating shaft 51 by an associated sleeve-like connector 55 that accommodates the relative longitudinal axial sliding movements of the operating shaft 51 with respect to the shaft 54, while maintaining the normal rotary connection therebetween. Further, the program controller 50 comprises a timer motor TM and a position advance motor PA, both of the synchronous type and preferably "Telechron" motors. The timer motor TM comprises an operating shaft 56 that is connected by a gear box 57 and an overrunning clutch 58 to the inner end of the shaft 54; and the position advance motor PA comprises an operating shaft 56' that is connected by a gear box 57' and an overrunning clutch 58' to the inner end of a shaft 54' that is mounted for rotation adjacent to the shaft 54. Also, the intermediate portions of the shafts 54 and 54' respectively carry gears 59 and 59' that are meshed. In the arrangement, energization of the timer motor TM effects rotation of the operating shaft 51 at a relatively slow speed in the clockwise direction and on a timed basis; whereas energization of the position advance motor PA effects rotation of the operating shaft 51 at a relatively fast speed in the clockwise direction and without reference to time. The overrunning clutches 58 and 58' prevent interference between the motors TM and PA, and also accommodate manual rotation of the operating shaft 51 in the clockwise direction under the direct control of the manual dial 52.

Further, the program controller 50 comprises longitudinal or axial reset mechanism, as shown in FIG. 5, and that essentially comprises a ring 61 rigidly affixed to the operating shaft 51 and carrying an outwardly or radially projecting pin 62. In turn, the pin 62 cooperates with a reset spring 63 that is externally supported, as indicated at 64. In the arrangement, when the operating shaft 51 occupies its "rotary start" or off position illustrated in FIG. 5, the manual dial 52 may be manually moved by the operator outwardly with respect to the front wall 101; whereby the operating shaft 51 is moved from its "axial

stop" position into its "axial start" position. When the operating shaft 51 is thus moved into its "axial start" position, the line switch 60 is closed and the pin 62 carried by the ring 61 is moved axially outwardly with respect to the extreme outer end of the reset spring 63 (the pin 62 is moved above the extreme outer end of the reset spring 63, as illustrated in FIG. 5). As explained more fully hereinafter, at this time, the motors TM and PA effect rotation of the operating shaft 51 in the clockwise direction and out of its normal "rotary start" position. After approximately 330° of such rotation of the operating shaft 51 in the clockwise direction, the pin 62 is rotated below the extreme outer end of the reset spring 63 so that continued rotation of the operating shaft 51 in the next 30° and back into its "rotary start" position causes cooperation between the pin 62 and the extreme outer end of the reset spring 63 so that the operating shaft 51 is moved inwardly with respect to the front wall of the backsplash 29 (downwardly with reference to the reset spring 63, as viewed in FIG. 5) and back into its "axial stop" position. When the operating shaft 51 is thus moved back into its "axial stop" position the line switch 60 is opened in order to terminate operation of the motors TM and PA, whereby further rotation of the operating shaft 51 is arrested when it occupies its "rotary start" position, as well as its "axial stop" position.

Referring now to FIG. 2, the stationary ring-like index plate 53, with which the manual dial and index pointer 52 cooperates, carries the circumferentially arranged indicia: "Off," "First Wash," "Spin," "Second Wash," "Spin," "Bonus Rinse," "Spin," "Final Rinse," and "Final Spin." As the cycle of the machine proceeds, the operating shaft 51 of the program controller 50 is rotated out of its "rotary start" position, causing the index pointer 52 to be rotated out of its corresponding "Off" position, these rotations being in the clockwise direction, as viewed in FIG. 2; whereby the progress of the cycle is indicated by the cooperation of the index pointer 52 with the index plate 53 in an obvious manner.

Considering now the general mode of operation of the program controller 50, rotation of the drive shaft from the gear box 57, in the clockwise direction, causes the friction clutch 58 to rotate the shaft 54 and the gear 59 in the clockwise direction, with the result that the gear 59 rotates the gear 59' and the shaft 54' in the counter clockwise direction. The friction clutch 58' permits such rotation of the shaft 54' with respect to the drive shaft extending from the gear box 57'; thereby to prevent interference by the motor PA with operation of the motor TM to rotate the shaft 54 in the clockwise direction at 1 r.p.h.

Rotation of the drive shaft extending from the gear box 57', in the counter clockwise direction, causes the friction clutch 58' to rotate the shaft 54' and the gear 59' in the counter clockwise direction, with the result that the gear 59' rotates the gear 59 and the shaft 54 in the clockwise direction. The friction clutch 58 permits such rotation of the shaft 54 with respect to the drive shaft extending from the gear box 57; thereby to prevent interference by the motor TM with operation of the motor PA to rotate the shaft 54 in the clockwise direction at 1 r.p.m.

When the motor TM is operated, while the motor PA is stopped, the clutch 58 effects the drive to the shaft 54, and the clutch 58' accommodates overdrive of the slow-running shaft 54' with respect to the stalled shaft extending to the gear box 57'; whereby the operating shaft 51 is rotated in the clockwise direction at 1 r.p.h. On the other hand, when the motor PA is operated, simultaneously with operation of the motor TM, the clutch 58' effects the drive to the shaft 54', and thence via the gears 59', 59 to the shaft 54, and the clutch 58 accommodates overdrive of the fast-running shaft 54 with respect to the slow-running shaft 54' extending to the gear box 57; whereby the operating shaft 51 is rotated in the clockwise direction at 1 r.p.m.

The ratio between the gears 59, 59' may be 1:1, since the speeds of the two shafts respectively extending from

the gear boxes 57 and 57' may be established by the two gear trains respectively arranged in the two boxes 57 and 57'.

Considering now in greater detail the control circuit, as illustrated in FIGS. 3, 4 and 5, the same comprises a terminal block 200 to which a source of electric power supply of 118-volts, single-phase, 60 cycle, A.-C., is connected; this source including two line conductors L1 and L2. Also, the machine 10 comprises a thermal protective device 201 and a balance switch 202'. The thermal protective device 201' may be of any suitable type, such, for example, as a resettable circuit breaker operative into an open position in response to an overload current condition for a given short time interval. The balance switch 202' may be of any conventional type and is operative from a normal closed position into an open position in response to abnormal vibration of the machine 10, such as may occur in a spinning operation of the spin tub 20 with a heavy unbalanced load of clothes therein. In the circuit, the line conductor L2 is connected via the thermal protective device 201' and the balance switch 202' in series relation to a supply conductor 206.

Considering now in greater detail the wiring diagram, the switch springs of the program controller 50 terminate the conductors as follows:

Switch Spring	Terminated Conductor	Switch Spring	Terminated Conductor
CW-----	201	J1-----	215
C1-----	202	K2-----	208

In the switch 110: the switch springs 113 and 114 are commonly connected to the conductor 222; the switch spring 115 is connected to the conductor 226; and the contacts respectively governed by the switch springs 113, 114 and 115 are respectively connected to the conductors 224, 228 and 223. In the switch 120: the switch spring 123 is connected to the conductor 204; and the contact governed by the switch spring 123 is connected to the conductor 201. In the switch 130: the switch spring 133 is connected to the conductor 218; and the contact governed by the switch spring 133 is connected to the conductor 217. In the switch 140: the switch springs 143 and 144 are commonly connected to the conductor 211; and the contacts respectively governed by the switch springs 143 and 144 are respectively connected to the conductors 225 and 227. In the switch 150: the switch springs 153 and 154 are commonly connected to the conductor 223; and the contacts respectively governed by the switch springs 153 and 154 are respectively connected to the conductors 221 and 218. In the switch 160: the switch spring 163 is connected to the conductor 204; and the contact governed by the switch spring 163 is connected to the conductor 203. In the switch 170: the switch springs 173 and 174 are commonly connected to the conductor 213; and the contacts respectively governed by the switch springs 173 and 174 are respectively connected to the conductors 225 and 227. In the switch 180: the contact segments 184, 185 and 186 are respectively connected to the conductors 208, 210 and 207. In the switch 190: the contact segments 194, 195 and 196 are respectively connected to the conductors 224, 219 and 220.

The hot solenoid 27a is bridged across the conductors 212 and 204; the cold solenoid 28a is bridged across the conductors 212 and 202; the bleach solenoid 35a is bridged across the conductors 212 and 209; and the detergent solenoid 30a is bridged across the conductors 228 and 204.

In the drive motor 40: the 4-pole start winding 44 is bridged across the conductors 214 and 216; the 4-pole run winding 42 is bridged across the conductors 208 and 225; and the 6-pole run winding 43 is bridged across the conductors 208 and 229. Also, the back contacts governed by the contact bridging member 48 respectively terminate the conductors 205 and 205; the front contacts governed by the contact bridging member 48 respectively terminate the conductors 206 and 208; the back contacts governed by the contact bridging member 49 respectively terminate the conductors 227, 225 and 215; and the front contacts governed by the contact bridging member 49 respectively terminate the conductors 227 and 229.

In the program controller 50: the timer motor TM is bridged across the conductors 206 and 226; the position advance motor PA is bridged across the conductors 206 and 224; and the contacts governed by the contact bridging member 60 of the line switch respectively terminate the conductors 226 and L1.

Before proceeding with the particular controls that are carried out by the program controller 50 in conjunction with the various switches 110, etc., in the automatic cycle of operation of the control circuit, reference is first made to FIG. 6, wherein there are disclosed the fundamental

items of the program controller 50, including the control cams 7B, etc., the switch spring sets CW-C1-HR, etc., respectively governed by the control cams 7B, etc., as well as the sequence of the opening and the closing of the contact sets in the cycle of operation of the program controller 50. This chart is read from left to right; and the closure time intervals of each pair of switch springs are indicated by solid or filled-in blocks. For example: the control cam 7B actuates the switch spring C1 to close the switch spring CW and to open the switch spring HR during the first eight steps or time intervals of the cycle; the control cam 7B then actuates the switch spring C1 to open both of the switch springs CW and HR during the next twenty-two steps of the cycle; the control cam 7B then actuates the switch C1 to open the

switch CW and to close the switch spring HR during the next twenty-two steps of the cycle; etc. Of course, the other control cams 6B, etc., govern the other switch spring sets H-MC-PR, etc., in a similar manner and simultaneously in the cycle of the program controller 50, as is evident from an examination of this chart.

Now assuming that an automatic program is to be carried out in the machine 10, when the manual dial 52 occupies its "rotary start" or "off" position and that the operating shaft 51 is in its "axial stop" position, the circuits are in the condition illustrated in FIG. 5 and indicated in FIG. 6. Further, assuming that in the program: two washes are desired, so that the tab 112 in the switch 110 is depressed; hot first wash is desired, so that the tab 121 in the switch 120 is depressed; no soak is desired between the two sections of the first wash, so that the tab 132 in the switch 130 is depressed; normal agitation in the washes is desired, so that the tab 141 in the switch 140 is depressed; two rinses are desired, so that the tab 152 in the switch 150 is depressed; warm rinses are desired, so that the tab 161 in the switch 160 is depressed; normal spinning in the water-extractions are desired, so that the tab 171 is depressed; a normal load is indicated, so that the control dial 182 of the switch 180 is rotated to its "normal load" position; and that a wash time interval of 10 minutes is indicated, so that the control dial 192 of the switch 190 is rotated to its "10-minutes" position. At this time the circuits are in the preselected condition illustrated in FIGS. 3, 4 and 5; and hereinafter, this particular program thus prese-

lected is referred to as the "basic program" as a standard of comparison.

Also, it may be assumed that the detergent dispenser 30 contains a suitable liquid detergent and the bleach dispenser 35 contains a suitable liquid bleaching agent. Further, it may be assumed that each of these liquid dispensers is responsive to energization and subsequent de-energization of the solenoid thereof to effect operation thereof to dispense into the spin tub 20 a measured charge of the corresponding contained liquid.

The operator then places the clothes and the required initial detergent in the spin tub 20, and closes the top door 14. In order to initiate this preselected basic program, the operator merely manually pulls the control dial 52 of the program controller 50 outwardly with respect to the front wall 101, whereby the operating shaft 51 is moved from its "axial stop" position into its "axial start" position, so as to close the line switch 60.

In the present example, closure of the line switch 60 completes a circuit for operating the timer motor TM via the elements L1, 60, 226, TM, 206, 202, 201, L2; whereby the timer motor TM drives or rotates the operating shaft 51 of the program controller 50 in the clockwise direction, as viewed in FIG. 2, out of its "rotary start" or "off" position (also, #1 position as illustrated in the chart of FIG. 6), the drive connection including the elements TM, 56, 57, 58, 54, 55 and 51. Also, it is noted that at this time, since the operating shaft 51 occupies its "axial start" position, the pin 62 is disposed outwardly of the reset spring 63 (above the reset spring 63); which arrangement is subsequently involved in resetting the operating shaft 51 back into its "axial stop" position, as explained hereinafter. Also, closure of the line switch 60 completes a circuit for energizing the hot solenoid 27a, this circuit including the elements L1, 60, 226, P3, B1, 223, 154, 218, P5, SS, 217, P6, E, 212, 27a, 204, H, MC, 205, 48, 206, 202, 201, L2. Energization of the hot solenoid 27a effects opening of the hot water valve 27, whereby hot water is introduced from the hot water pipe 24 via the tube 26 into the spin tub 20.

After a time interval of 4 minutes, the operating shaft 51 of the program controller 50 is rotated into position #5 (see the chart of FIG. 6; whereby the control cam 5B actuates the switch spring F2 to close the switch spring NF, thereby to complete forward start and run circuits for respectively energizing the start and run windings 44 and 42 of the drive motor 40. The forward start circuit mentioned includes the elements L1, 60, 226, P3, B1, 223, 154, 218, P5, SS, 217, P6, E, 212, MP, W, 211, 143, 225, 49, 215, J1, S2, 214, 44, 216, S4, K2, 208, 184, 183, 185, 210, NF, F2, 206, 202, 201, L2; and the forward run circuit mentioned includes the elements L1, 60, 226, P3, B1, 223, 154, 218, P5, SS, 217, P6, E, 212, MP, W, 211, 143, 225, 42, 208, 184, 183, 185, 210, NF, F2, 206, 202, 201, L2. The drive motor 40 starts rotating its rotor 41 in the forward direction; whereby the centrifugal device 46 actuates the bridging members 48 and 49, when the rotor 41 gains about 60% of its normal running speed. Specifically, the device 46 actuates the bridging members 48 and 49 to open their back contacts and to close their front contacts. Opening of its back contacts by the bridging member 49, interrupts the forward start circuit for the start winding 44. Opening of the back contacts by the bridging member 48, interrupts the previously traced circuit for the hot solenoid 27a; whereby the hot water valve 27 returns to its closed position to cut-off the supply of hot water to the spin tub 20.

Closure of the front contacts by the bridging member 48, completes a forward holding circuit for energizing the run winding 42 of the drive motor 40; this forward holding circuit includes the elements L1, 60, 226, P3, B1, 223, 154, 218, P5, SS, 217, P6, E, 212, MP, W, 211, 143, 225, 42, 208, 48, 206, 202, 201, L2. Closure of the

forward holding circuit effects continued energization of the run winding 42, so that the rotor 41 accelerates on into its normal running speed of about 1725 r.p.m. in the forward direction, in order to effect oscillation of the agitator 22 at its normal rate of about 64 cycles per minute to produce a normal washing action upon the clothes suspended in the hot water in the spin tube 20. It is noted that operation of the drive motor 40 was thus initiated in position #5 of the operating shaft 51; whereby the hot water valve 27 was closed, as described above, with the result that the hot water was supplied into the spin tube 19a during a corresponding time interval of 4 minutes, producing a normal fill of hot water therein for use in the wash cycle.

When the operating shaft 51 is rotated into position #10, the control cam 5B actuates the switch spring F2 to close the switch spring BD; and when the operating shaft 51 is rotated into position #12, the control cam 5B actuates the switch spring F2 to open the switch spring BD; whereby a circuit is completed and then interrupted for energizing the solenoid 35a of the bleach dispenser, so as to cycle the same in order to cause a measured charge of the liquid bleach agent to be introduced via the tube 36 into the spin tub 20. The above-mentioned circuit for energizing the bleach solenoid 35a, when completed, includes the elements L1, 60, 226, P3, B1, 223, 154, 218, 133, 217, P6, E, 212, 35a, 209, BD, F2, 206, 202, 201, L2.

When the operating shaft 51 is rotated into position #13, the control cam 1B actuates the switch spring C2 to close the switch spring CR, so as to complete a circuit for energizing the cold solenoid 28a; this circuit including the elements L1, 60, 226, P3, B1, 223, 154, 218, 133, 217, P6, E, 212, 28a, 202, C2, CR, 205, MC, PR, 206, 202, 201, L2. When the operating shaft 51 is rotated into position #14, the control cam 1B actuates the switch spring C2 to open the switch spring CR, so as to interrupt the circuit for the cold solenoid 28a. Thus, the cold water valve 28 is maintained open for a time interval of 1 minute, while the operating shaft occupies position #13, so as to cause cold water to be introduced via the tube 26 into the spin tub 20 during the first washing action in order to insure ample water in the spin tub 20 following the introduction of the liquid bleach thereto from the bleach dispenser in position #12 of the operating shaft 51.

The washing action thus initiated in position #5 of the operating shaft 51 continues for a time interval of 10 minutes, whereupon the operating shaft 51 is rotated into position #15, with the result that the control cam 2B actuates the switch spring MP to open the switch spring W. Opening of the switch springs MP, W interrupts the forward holding circuit for energizing the run winding 42 of the drive motor 40, so that the rotor 41 stops to terminate the washing action of the agitator 22 in the spin tub 20. Stopping of the rotor 41 causes the device 46 to reset the bridging members 48 and 49 into their back positions, as shown in FIG. 5.

After a time interval of 1 minute, the operating shaft 51 is rotated into position #16, whereupon the control cam 2B actuates the switch spring MP to close the switch spring S, thereby to complete reverse start and run circuits for respectively energizing the start and run windings 44 and 42 of the drive motor 40. The reverse start circuit mentioned includes the elements L1, 60, 226, P3, B1, 223, 154, 218, P5, SS, 217, P6, E, 212, MP, S, 213, 173, 225, 49, 215, J2, S4, 216, 44, 214, S2, K1, 208, ML, FL, 206, 202, 201, L2; and the reverse run circuit mentioned includes the elements L1, 60, 226, P3, B1, 223, 154, 218, P5, SS, 217, P6, E, 212, MP, S, 213, 173, 225, 42, 208, ML, FL, 206, 202, 201, L2. The drive motor 40 starts rotating its rotor 41 in the reverse direction; whereby the centrifugal device 46 actuates the bridging members 48 and 49 at about 60% normal running speed.

Specifically, the bridging member 49 interrupts the reverse start circuit; and the bridging member 48 completes a reverse holding circuit for energizing the run winding 42 of the drive motor 40; which reverse holding circuit includes the elements L1, 60, 226, P3, B1, 223, 154, 218, P5, SS, 217, P6, E, 212, MP, S, 213, 173, 225, 42, 208, 48, 206, 202, 201, L2. The rotor 41 then accelerates into its normal running speed of about 1725 r.p.m. in the reverse direction; thereby to effect spinning of the spin tub 20 at its normal speed of about 640 r.p.m. to produce a normal water-extraction action upon the clothes therein. The wash water spun from the spin tub 20 is caught in the drain tub 15 and pumped to the drain plumbing, not shown, in the usual manner.

Also, in position #16 of the operating shaft 51, the control cam 1B actuates the switch spring C2 to close the switch spring CR, thereby to complete a circuit for energizing the cold solenoid 28a, so as to effect opening of the cold water valve 28; with the result that cold water is introduced from the cold water pipe 25 via the tube 26 into the spin tube 20 during spinning thereof. This effects a spraying action upon the clothes as they are spun in the spin tub 20; and the water thus introduced into the spin tub 20 is expelled therefrom and caught in the drain tub 15 and then pumped to the drain plumbing, as previously explained. The circuit noted above for energizing the cold solenoid 28a includes the elements L1, 60, 226, P3, B1, 223, 154, 218, P5, SS, 217, P6, E, 212, 28a, 202, C2, CR, 205, NC, PR, 206, 202, 201, L2.

Subsequently, after a time interval of 1 minute, the operating shaft 51 is rotated into position #17, whereby the control cam 1B actuates the switch spring CR to open the switch spring C2, thereby to interrupt the circuit for energizing the cold solenoid 28a, so as to effect closing of the cold valve 28 in order to terminate the introduction of cold water from the cold water pipe 25 via the tube 26 into the spinning spin tub 20, with the result that the spray action described above is terminated.

The spinning of the spin tub 20 initiated in position #16 of the operating shaft 51 continues for a time interval of 3 minutes, whereupon the operating shaft 51 is rotated into position #19, with the result that the control cam 2B actuates the switch spring MP to open the switch spring S. Opening of the switch spring, MP, S interrupts the reverse holding circuit for energizing the run winding 42 of the drive motor 40, so that the rotor 41 stops to terminate the spinning of the spin tub 20. Stopping of the rotor 41 causes the device 46 to reset the bridging members 48 and 49 into their back positions, as shown in FIG. 5.

After a time interval of 1 minute, the operating shaft 51 is rotated into position #20, whereby the control cam 6B actuates the switch spring MC to close the switch spring H, thereby to complete a circuit for energizing the detergent solenoid 30a; this circuit including the elements L1, 60, 226, P3, A3, 222, 114, 228, 30a, 204, H, MC, 205, 48, 206, 202, 201, L2.

Also, closure of the switch springs MC, H complete a circuit for energizing the hot solenoid 27a; this circuit including the elements L1, 60, 226, 115, 223, 154, 218, P5, SS, 217, P6, E, 212, 27a, 204, H, MC, 205, 48, 206, 202, 201, L2. Energization of the hot solenoid 27a effects opening of the hot water valve 27, whereby hot water is introduced from the hot water pipe 24 via the tube 26 into the spin tub 20.

At this point, it is noted that the above-traced circuit for energizing the hot solenoid 27a is independent of the positions of the control switch 120; and since the control cam 7B maintains open the switch springs C1, CW, there is no possibility of energization of the cold solenoid 28a at this time. Thus, the second wash cycle always proceeds employing hot water in the spin tub 20.

After a time interval of 4 minutes, the operating shaft 51 is rotated into position #24, whereby the con-

trol cam 5B actuates the switch spring F2 to close the switch spring NF, thereby to complete forward start and run circuits for respectively energizing the start and run windings 44 and 42 of the drive motor 40. The forward start circuit mentioned includes the elements L1, 60, 226, 115, 223, 154, 218, P5, SS, 217, P6, E, 212, MP, W, 211, 143, 225, 49, 215, J1, S2, 216, 44, 216, S4, K2, 208, 184, 183, 185, 210, NF, F2, 206, 202, 201, L2; and the forward run circuit mentioned includes the elements L1, 60, 226, 115, 223, 154, 218, P5, SS, 217, P6, E, 212, MP, W, 211, 143, 225, 42, 208, 184, 183, 185, 210, NF, F2, 206, 202, 201, L2. The drive motor 40 starts rotating its rotor 41 in the forward direction; whereby the device 46 actuates the bridging members 48 and 49 in the manner previously explained. Specifically, the bridging member 49 opens its back contacts to interrupt the start circuit for the start winding 44. The bridging member 48 opens its back contacts to interrupt the circuit for energizing the detergent solenoid 30a and the circuit for energizing the hot solenoid 27a. The detergent dispenser 30 completes its cycle to introduce a measured charge of detergent via the tube 31 into the spin tub 20; and the hot water valve 27 returns to its closed position to cut-off the supply of hot water to the spin tub 20. Closure of its front contacts by the bridging member 48 completes a forward holding circuit for energizing the run winding 42 of the drive motor 40; this forward holding circuit including the elements L1, 60, 226, 115, 223, 154, 218, P5, SS, 217, P6, E, 212, MP, W, 211, 143, 225, 42, 208, 48, 206, 202, 201, L2. Closure of the forward holding circuit effects continued energization of the run winding 42, so that the rotor 41 accelerates on into its normal running speed of about 1725 r.p.m. in the forward direction in order to effect oscillation of the agitator 22 at its normal rate of about 64 cycles per minute to produce a normal washing action upon the clothes suspended in the hot water in the spin tub 20 in the usual manner. It is noted that the hot water valve 27 was opened in position #20 of the operating shaft 51 and was closed in position #24 of the operating shaft 51, whereby hot water was introduced into the spin tub 20 during a time interval of 4 minutes, so as to produce a normal fill of hot water therein for use in the wash cycle.

The washing action thus initiated in position #24 of the operating shaft 51 continues for a time interval of 3 minutes, whereupon the operating shaft 51 is rotated into position #27, with the result that the control cam 2B actuates the switch spring MP to open the switch spring W to interrupt the forward holding circuit for the run winding 42 of the drive motor 40, so that the rotor 41 stops to terminate the washing action of the agitator 22 in the spin tub 20. Also, the device 46 resets the bridging members 48 and 49 into their back positions, as shown in FIG. 5.

After a time interval of 1 minute, the operating shaft 51 is rotated into position #28, whereupon the control cam 2B actuates the switch spring MP to close the switch spring S, thereby to complete reverse start and run circuits for respectively energizing the start and run windings 44 and 42 of the drive motor 40. The reverse start circuit mentioned includes the elements L1, 60, 226, 115, 223, 154, 218, P5, SS, 217, P6, E, 212, MP, S, 213, 173, 225, 49, 215, J2, S4, 216, 44, 214, S2, K1, 208, ML, FL, 206, 202, 201, L2; and the reverse run circuit mentioned includes the elements L1, 60, 226, 115, 223, 154, 218, P5, SS, 217, P6, E, 212, MP, S, 213, 173, 225, 42, 208, ML, FL, 206, 202, 201, L2. The drive motor 40 starts rotating its rotor 41 in the reverse direction; whereby the device 46 actuates the bridging members 48 and 49 in the manner previously explained. Specifically, the bridging member 49 interrupts the reverse start circuit; and the bridging member 48 completes a reverse holding circuit for energizing the run winding 42 of the drive motor 40; which reverse holding circuit

includes the elements L1, 60, 226, 115, 223, 154, 218, P5, SS, 217, P6, E, 212, MP, S, 213, 173, 225, 42, 208, 48, 206, 202, 201, L2. The rotor 41 then accelerates into the normal running speed of about 1725 r.p.m. in the reverse direction; thereby to effect spinning of the spin tub 20 at its normal speed of about 640 r.p.m. to produce a normal water-extraction action upon the clothes therein. The wash water spun from the spin tub 20 is caught in the drain tub 15 and pumped to the previously mentioned drain plumbing.

Also, in position #28 of the operating shaft 51, the control cam 1B actuates the switch spring C2 to close the switch spring CR, thereby to complete a circuit for energizing the cold solenoid 28a, so as to effect opening of the cold water valve 28, with the result that cold water is introduced from the cold water pipe 25 via the tube 26 into the spin tub 20 during spinning thereof. This effects a spraying action upon the clothes as they are spun in the spin tub 20; and the water thus introduced into the spin tub 20 is expelled therefrom and caught in the drain tub 15 and then pumped to the drain plumbing. The circuit noted above for energizing the cold solenoid 28a includes the elements L1, 60, 226, 115, 223, 154, 218, P5, SS, 217, P6, E, 212, 28a, 202, C2, CR, 205, MC, PR, 206, 202, 201, L2.

Subsequently, after a time interval of 1 minute, the operating shaft 51 is rotated into position #29, whereby the control cam 1B actuates the switch spring CR to open the switch spring C2, thereby to interrupt the circuit for energizing to cold solenoid 28a, so as to effect closing of the cold valve 28 in order to terminate the introduction of cold water from the cold water pipe 25 via the tube 26 into the spinning spin tub 20, with the result that the spray action described above is terminated.

The spinning of the spin tub 20 initiated in position #28 of the operating shaft 51 continues for a time interval of 3 minutes, whereupon the operating shaft 51 is rotated into position #31, with the result that the control cam 2B actuates the switch spring MP to open the switch spring S to interrupt the reverse holding circuit for the run winding 42 of the drive motor 40, so that the rotor 41 stops to terminate the spinning of the spin tub 20. Also, the device 46 resets the bridging members 48 and 49 into their back positions, as shown in FIG. 5.

After a time interval of 1 minute, the operating shaft 51 is rotated into position #32, whereby the control cam 1B actuates the switch spring C2 to close the switch spring CR, thereby to complete a circuit for energizing the hot solenoid 27a and also a circuit for energizing the cold solenoid 28a, whereby both the hot water valve 27 and the cold water valve 28 are opened with the result that hot water from the hot water pipe 24 and cold water from the cold water pipe 25 are mixed to produce warm water that is introduced via the tube 26 into the spin tub 20. The circuit for energizing the hot solenoid 27a includes the elements L1, 60, 226, P3, B1, 223, 154, 218, P5, SS, 217, P6, E, 212, 27a, 204, 163, 203, HR, C1, 202, C2, CR, 205, 48, 206, 202, 201, L2; and the circuit for energizing the cold solenoid 28a includes the elements L1, 60, 226, P3, B1, 223, 154, 218, P5, SS, 217, P6, E, 212, 28a, 202, C2, CR, 205, 48, 206, 202, 201, L2.

After a time interval of 4 minutes, the operating shaft 51 is rotated into position #36, whereby the control cam 5B actuates the switch spring F2 to close the switch spring NF, thereby to complete forward start and run circuits for respectively energizing the start and run windings 44 and 42 of the drive motor 40. The forward start circuit mentioned includes the elements L1, 60, 226, P3, B1, 223, 154, 218, P5, SS, 217, P6, E, 212, MP, W, 211, 143, 225, 49, 215, J1, S2, 214, 44, 216, S4, K2, 208, 184, 183, 185, 210, NF, F2, 206, 202, 201, L2; and the forward run circuit mentioned includes the elements L1, 60, 226, P3, B1, 223, 154, 218, P5, SS, 75

217, P6, E, 212, MP, W, 211, 143, 225, 42, 208, 184, 183, 185, 210, NF, F2, 206, 202, 201, L2. The drive motor 40 starts rotating its rotor 41 in the forward direction; whereby the drive 46 actuates the bridging members 48 and 49 in the manner previously explained. Specifically, the bridging member 49 opens its back contacts to interrupt the start circuit for the start winding 44. The bridging member 48 opens its back contacts to interrupt the circuits for the hot solenoid 27a and cold solenoid 28a, whereby the hot water valve 27 and the cold water valve 28 are returned to their closed positions to cut-off the supply of warm water to the spin tube 20. Also, the bridging member 48 completes a forward holding circuit for energizing the run winding 42 of the drive motor 40; this forward holding circuit including the elements L1, 60, 226, P3, B1, 223, 154, 218, P5, SS, 217, P6, E, 212, MP, W, 211, 143, 225, 42, 208, 48, 206, 202, 201, L2. Closure of the forward holding circuit effects continued energization of the run winding 42, so that the rotor 41 accelerates on into its normal running speed of about 1725 r.p.m. in the forward direction in order to effect oscillation of the agitator 22 at its normal rate of about 64 cycles per minute to produce a deep agitated rinsing action upon the clothes suspended in the warm water in the spin tub 20 in the usual manner. It is noted that the hot water valve 27 and the cold water valve 28 were opened in position #32 of the operating shaft 51 and were closed in position #36 of the operating shaft 51, whereby warm water was introduced into the spin tub 20 during a time interval of 4 minutes, so as to produce a normal fill of warm water therein for use in the bonus rinse cycle.

The deep agitated rinsing action thus initiated in position #36 of the operating shaft 51 continues for a time interval of 2 minutes whereupon the operating shaft 51 is rotated into position #38, with the result that the control cam 2B actuates the switch spring MP to open the switch spring W to interrupt the forward holding circuit for the run winding 42 of the drive motor 40, so that the motor 41 stops to terminate the deep agitated rinsing action. Also, the device 46 resets the bridging members 48 and 49 into their back positions, as shown in FIG. 5.

After a time interval of 1 minute, the operating shaft 51 is rotated into position #39, whereupon the control cam 2B actuates the switch spring MP to close the switch spring S, thereby to complete reverse start and run circuits for respectively energizing the start and run windings 44 and 42 of the drive motor 40. The reverse start circuit mentioned includes the elements L1, 60, 226, P3, B1, 223, 154, 218, P5, SS, 217, P6, E, 212, MP, S, 213, 173, 225, 49, 215, J2, S4, 216, 44, 214, S2, K1, 208, ML, FL, 206, 202, 201, L2; and the reverse run circuit mentioned includes the elements L1, 60, 226, P3, B1, 223, 154, 218, P5, SS, 217, P6, E, 212, MP, S, 213, 173, 225, 42, 208, ML, FL, 206, 202, 201, L2. The drive motor 40 starts rotating its rotor 41 in the reverse direction; whereby the device 46 actuates the bridging members 48 and 49 in the manner previously explained. Specifically, the bridging member 49 interrupts the reverse start circuit; and the bridging member 48 completes a reverse holding circuit for energizing the run winding 42 of the drive motor 40; which reverse holding circuit includes the elements L1, 60, 226, P3, B1, 223, 154, 218, P5, SS, 217, P6, E, 212, MP, S, 213, 173, 225, 42, 208, 48, 206, 202, 201, L2. The rotor 41 then accelerates into its normal running speed of about 1725 r.p.m. in the reverse direction; thereby to effect spinning of the spin tub 20 at its normal speed of about 640 r.p.m. to produce a normal water-extraction action upon the clothes therein. The rinse water spun from the spin tub 20 is caught in the drain tub 15 and pumped to the previously mentioned drain plumbing.

Subsequently, after a time interval of 2 minutes, the operating shaft 51 is rotated into position #41, whereby

the control cam 2B actuates the switch spring MP to open the switch spring S to interrupt the reverse holding circuit for the run winding 42 of the drive motor 40, so that the rotor 41 stops to terminate the spinning of the spin tub 20. Also, the device 46 resets the bridging members 48 and 49 into their back positions, as shown in FIG. 5.

After a time interval of 1 minute, the operating shaft 51 is rotated into position #42, whereby the control cam 5B actuates the switch spring F2 to close the switch spring BD, so as to complete a circuit for energizing the bleach solenoid 35a. This circuit includes the elements L1, 60, 226, P3, B1, 223, 154, 218, P5, SS, 217, P6, E, 212, 35a, 209, BD, F2, 206, 202, 201, L2.

Also, in position #42 of the operating shaft 51, the control cam 1B actuates the switch spring C2 to close the switch spring CR, thereby to complete a circuit for energizing the hot solenoid 27a and also a circuit for energizing the cold solenoid 28a, whereby both the hot water valve 27 and the cold water valve 28 are opened to effect the introduction of warm water via the tube 26 into the spin tub 20, in the manner previously explained. The circuit for energizing the hot solenoid 27a includes the elements L1, 60, 226, P3, B1, 223, 154, 218, P5, SS, 217, P6, E, 212, 27a, 204, 163, 203, HR, C1, 202, C2, CR, 205, MC, PR, 206, 202, 201, L2; and the circuit for energizing the cold solenoid 28a includes the elements L1, 60, 226, P3, B1, 223, 154, 218, P5, SS, 217, P6, E, 212, 28a, 202, C2, CR, 205, 48, 206, 202, 201, L2.

After a time interval of 4 minutes, the operating shaft 51 is rotated into position #46, whereby the control cam 5B actuates the switch spring F2 to close the switch spring NF, thereby to complete forward start and run circuits for respectively energizing the start and run windings 44 and 42 of the drive motor 40. The forward start circuit mentioned includes the elements L1, 60, 226, P3, B1, 223, 154, 218, P5, SS, 217, P6, E, 212, MP, W, 211, 143, 225, 49, 215, J1, S2, 214, 44, 216, S4, K2, 208, 184, 183, 185, 210, NF, F2, 202, 201, L2; and the forward run circuit mentioned includes the elements L1, 60, 226, P3, B1, 223, 154, 218, P5, SS, 217, P6, E, 212, MP, W, 211, 143, 225, 42, 208, 184, 183, 185, 210, NF, F2, 206, 202, 201, L2. The drive motor 40 starts rotating its rotor 41 in the forward direction; whereby the device 46 actuates the bridging members 48 and 49 in the manner previously explained. Specifically, the bridging member 49 opens its back contacts to interrupt the start circuit for the start winding 44. The bridging member 48 opens its back contacts to interrupt the circuits for the hot solenoid 27a and the cold solenoid 28a, whereby the hot water valve 27 and the cold water valve 28 are returned to their closed positions to cut-off the supply of warm water to the spin tub 20. Also, the bridging member 49 completes a forward holding circuit for energizing the run winding 42 of the drive motor 40; this forward holding circuit including the elements L1, 60, 226, P3, B1, 223, 154, 218, P5, SS, 217, P6, E, 212, MP, W, 211, 143, 225, 42, 208, 48, 206, 202, 201, L2. Closure of the forward holding circuit effects continued energization of the run winding 42, so that the rotor 41 accelerates on into its normal running speed of about 1725 r.p.m. in the forward direction in order to effect oscillation of the agitator 22 at its normal rate of about 64 cycles per minute to produce a deep agitated rinsing action upon the clothes suspended in the warm water in the spin tub 20 in the usual manner. It is noted that the hot water valve 27 and the cold water valve 28 were opened in position #42 of the operating shaft 51 and were closed in position #46 of the operating shaft 51, whereby warm water was introduced into the spin tub 20 during a time interval of 4 minutes, so as to produce a normal fill of warm water there for use in the final rinse cycle.

Also, in position #46 of the operating shaft 51, the control cam 5B actuates the switch spring F2 to open the

switch spring BD, so as to interrupt the circuit for the bleach solenoid 35a, thereby to cycle the bleach dispenser 35, with the result that a measured charge of the liquid bleaching agent is introduced via the tube 36 into the spin tub 20.

After a time interval of 1 minute, the operating shaft 51 is rotated into position #47, whereby the control cam 3B actuates the switch spring FL to close the switch spring ML, thereby to complete a circuit for energizing the hot solenoid 27a and also a circuit for energizing the cold solenoid 28a, whereby both the hot water valve 27 and the cold water valve 28 are opened to effect the introduction of warm water via the tube 26 into the spin tub 20 during oscillation of the agitator 22, so as to produce overflow of the warm water from the spin tub 20 and the consequent deep overflow agitated rinsing action upon the clothes in the spin tub 20. The circuit for energizing the hot solenoid 27a includes the elements L1, 60, 226, P3, B1, 223, 154, 218, P5, SS, 217, P6, E, 212, 27a, 204, 163, 203, HR, C1, 202, C2, CR, 205, MC, PR, 206, 202, 201, L2; and the circuit for energizing the cold solenoid 28a includes the elements L1, 60, 226, P3, B1, 223, 154, 218, P5, SS, 217, P6, E, 212, 28a, 202, C2, CR, 205, MC, PR, 206, 202, 201, L2.

After a time interval of 2 minutes, the operating shaft 51 is rotated into position #49, whereby the control cam 1B actuates the switch spring C2 to open the switch spring C2, thereby to interrupt the circuits for the hot solenoid 27a and the cold solenoid 28a, with the result that the hot water valve 27 and the cold water valve 28 are returned into their closed positions to terminate the supply of warm water into the spin tub 20, so as to terminate the water overflow in the deep agitated rinsing action.

After a time interval of 1 minute, the operating shaft 51 is rotated into position #50, whereby the control cam 2B actuates the switch spring MP to open the switch spring W to interrupt the forward holding circuit for the run winding 42 of the drive motor 40, so that the rotor 41 stops to terminate the deep agitated rinsing action. Also, the device 46 resets the bridging members 48 and 49 into their back positions, as shown in FIG. 5.

After a time interval of 1 minute, the operating shaft 51 is rotated into position #51, whereupon the control cam B actuates the switch spring MP to close the switch spring S, thereby to complete reverse start and run circuits for respectively energizing the start and run windings 44 and 42 of the drive motor 40. The reverse start circuit mentioned includes the elements L1, 60, 226, P3, B1, 223, 154, 218, P5, SS, 217, P6, E, 212, MP, S, 213, 173, 225, 49, 215, J2, S4, 216, 44, 214, S2, K1, 208, ML, FL, 206, 202, 201, L2; and the reverse run circuit mentioned includes the elements L1, 60, 226, P3, B1, 223, 154, 218, P5, SS, 217, P6, E, 212, MP, S, 213, 173, 225, 42, 208, ML, FL, 206, 202, 201, L2. The drive motor 40 starts rotating its rotor 41 in the reverse direction; whereby the device 46 actuates the bridging members 48 and 49 in the manner previously explained. Specifically, the bridging member 49 interrupts the reverse start circuit; and the bridging member 48 completes a reverse holding circuit for energizing the run winding 42 of the drive motor 40; which reverse holding circuit includes the elements L1, 60, 226, P3, B1, 223, 154, 218, P5, SS, 217, P6, E, 212, MP, S, 213, 173, 225, 42, 208, 48, 206, 202, 201, L2. The rotor 41 then accelerates into its normal running speed of about 1725 r.p.m. in the reverse direction; thereby to effect spinning of the spin tub 20 at its normal speed of about 640 r.p.m. to produce a normal water-extraction action upon the clothes therein. The rinse water spun from the spin tube 20 is caught in the drain tub 15 and pumped to the previously mentioned drain plumbing.

Subsequently, after a time interval of 7 minutes, the operating shaft 51 is rotated into position #58, whereby the control cam 2B actuates the switch spring MP to open the switch spring S to interrupt the reverse holding cir-

cuit for the run winding 42 of the drive motor 40, so that the rotor 41 stops to terminate the final spinning of the spin tub 20. Also, the device 46 resets the bridging members 48 and 49 into their back positions, as shown in FIG. 5.

Also, in position #58 of the operating shaft 51, the control cam 2T actuates the switch spring P6 to close the switch spring BP, so as to complete a by-pass circuit for operating the time motor TM independently of the position of the line switch 60; this circuit includes the elements L1, BP, P6, 217, SS, P5, 218, 154, 223, B1, P3, 226, TM, 206, 202, 201, L2. In the subsequent rotation of the operating shaft 51 between position #58 and position #62, the pin 62 rides under the reset spring 63, as illustrated in FIG. 5; whereby the reset spring 63 acting upon the pin 62 forces the operating shaft 51 to move axially inwardly toward the front wall of the backsplash 29 (downwardly as shown in FIG. 5); whereby the operating shaft 51 is moved axially from its "axial start" position back into its "axial stop" position. This resetting of the operating shaft 51 back into its "axial stop" position effects opening of the line switch 60.

At this time, the operating circuit for the timer motor TM is maintained by virtue of the closed position of the switch spring P6 with respect to the switch spring BP. Thus rotation of the operating shaft 51 is continued so that the same is rotated through position #62 and back into position #1, the "rotary start" position of the operating shaft 51. In position #1, the operating shaft 51 causes the control cam 2T to actuate the switch spring P6 to open the switch spring BP and to close the switch spring E. Opening of the switch springs P6, BP interrupts the operating circuit for the timer motor TM, so as to arrest further rotation of the operating shaft 51 when it is in position #1. At this time the operating shaft 51 occupies both its "axial stop" position and its "rotary start" position; the circuits are back into the conditions illustrated in FIGS. 3, 4 and 5; and the preset basic program has been carried out by the program controller 50 on a timed basis. At this time, the operator may open the top door 14 and remove the clothes from the spin tub 20, since the washing and water-extracting actions have been performed thereupon in the machine 10 in the basic program described.

Consider now the presetting of a first modified program, modified with respect to the basic program in the particular that the desired time interval of oscillation of the agitator 22 in the first wash cycle is 7 minutes, instead of 10 minutes. The presetting of this first modified program is fundamentally the same as that previously described in conjunction with the presetting of the basic program, except that in this case, the operator rotates the manual dial 192 into its "7-minutes" position. The operator then manually pulls the control dial 52 outwardly with respect to the front wall 101 into its "axial start" position. At this time, the operating shaft 51 occupies position #1; and the line switch 60 is closed in response to movement of the operating shaft 51 into its "axial start" position.

The initial portion of this first modified program is the same as that of the basic program as described above; however, when the operating shaft 51 is rotated into position #7, the control cam 4B actuates the switch spring P2 to close the switch spring A1, thereby to complete a primary circuit for energizing the position advance motor PA. The primary circuit includes the elements L1, 60, 226, P2, A1, 219, 195, 193, 194, 224, PA, 206, 201, L2. The position advance motor PA drives the operating shaft 51 rapidly from position #7 to position #10, whereby the control cam 4B actuates the switch spring P2 to open the switch A1 to interrupt the primary circuit for the position advance motor PA. The operating position advance motor PA drives the operating shaft through the elements 56', 57', 58', 54', 59', 59, 54, 55; and the element 58 accommodates the overrunning and rapid drive of the shaft

54 with respect to the gear box 57 that is driven by the timer motor TM on a timed basis.

The remainder of the first modified program is the same as that of the basic program as previously described; and it will be understood that the present first modified program comprises a first wash time interval of 7 minutes.

Consider now the presetting of a second modified program, modified with respect to the basic program in the particular that the desired time interval of oscillation of the agitator 22 in the first wash cycle is 4 minutes instead of 10 minutes. The presetting of this second modified program is fundamentally the same as that previously described in conjunction with the presetting of the basic program, except that in this case, the operator rotates the manual dial 192 into its "4-minutes" position. The operator then manually pulls the control dial 52 outwardly with respect to the front wall 101 into its "axial start" position. At this time, the operating shaft occupies position #1; and the line switch 60 is closed in response to movement of the operating shaft 51 into its "axial start" position.

The initial portion of this second modified program is the same as that of the basic program, as previously described; however, when the operating shaft is rotated into position #7, the control cam 4B actuates the switch spring P2 to close the switch spring A1, thereby to complete the previously traced primary circuit for energizing the position advance motor PA, with the result that the operating shaft 51 is rapidly rotated from position #7 into position #10. In position #10 of the operating shaft 51 the control cam 4B actuates the switch spring P2 to open the switch spring A1 and to close the switch spring A2. Opening of the switch spring A1 interrupts the primary circuit for the position advance motor PA, while closing of the switch spring A2 completes a secondary circuit for energizing the position advance motor PA. This secondary circuit includes the elements L1, 60, 226, P2, A2, 220, 196, 193, 194, 224, PA, 206, 202, 201, L2. The position advance motor PA then drives the operating shaft 51 rapidly from position #10 to position #13, whereby the control cam 4B actuates the switch spring P2 to open the switch spring A2 to interrupt the secondary circuit for the position advance motor PA. Thus, it will be understood that the present second modified program comprises a first wash time interval of 4 minutes.

The intermediate portion of the second modified program is the same as that of the basic program; however when the operating shaft 51 is rotated into position #53, the control cam 4B actuates the switch P2 to close the switch spring A2 to complete the secondary circuit for energizing the position advance motor PA, with the result that the operating shaft 51 is rapidly rotated from position #53 into position #57. In position #57 of the operating shaft 51 the control cam 4B actuates the switch spring P2 to open the switch spring A2, so as to interrupt the secondary circuit for the position advance motor PA. Thus, it will be understood that the present second modified program comprises a final spin time interval of 3 minutes, instead of 7 minutes.

The conclusion of the second modified program is the same as that of the basic program as previously described.

Consider now the presetting of a third modified program, modified with respect to the basic program in the particular that only a partial fill of water, instead of a normal fill of water, is desired in the spin tub 20. The presetting of this third modified program is fundamentally the same as that previously described in conjunction with the presetting of the basic program, except that in this case, the operator rotates the manual dial 182 into its "small load" position, and then manually pulls the control dial 52 outwardly with respect to the front wall 101 into its "axial start" position. At this time, the operating shaft occupies position #1; and the line switch 60 is closed in response to movement of the operating shaft 51 into its "axial start" position.

The present third modified program is fundamentally the same as the basic program, except that in each of the four instances in which the spin tub 20 is filled with water, the drive motor 40 is started in the forward direction after the expiration of a fill time interval of 3 minutes, instead of after the normal fill time interval of 4 minutes. This is accomplished in each instance (in positions #4, #23, #35 and #45 of the operating shaft 51) by operation of the control cam 3B to actuate the switch spring FL to close the switch spring PF. Closure 10 of the switch springs FL, PF connects the conductor 208 to the conductor 207 and via the elements 186, 183, to the conductor 208, when the manual dial 182 occupies its "small load" position; whereby the forward start and run circuits for respectively energizing the start and run windings 44 and 42 are completed to initiate forward starting of the drive motor 40; with the result that the device 46 is operated to actuate the bridging member 48 to open its back contacts, so as to interrupt the circuits for the hot solenoid 27a or for both the hot solenoid 27a 20 and the cold solenoid 28a, as previously explained.

Thus, in the present third modified program the drive motor 40 is started 1 minute early with respect to the basic program, so that the water cut-off occurs early to provide the spin tub 20 with only a partial fill of water. Specifically, in the present third modified program each water fill time interval is 3 minutes, instead of 4 minutes, as in the basic program.

This present third modified program is otherwise the same as the basic program as previously described.

Consider now the presetting of a fourth modified program, modified with respect to the basic program in the particular that an extra fill of water, instead of a normal fill of water, is desired in the spin tub 20. The presetting of this fourth modified program is fundamentally the same as that previously described in conjunction with the presetting of the basic program, except that in this case, the operator rotates the manual dial 182 into its "large load" position, and then manually pulls the control dial 52 outwardly with respect to the front wall 101 into its 40 "axial start" position. At this time the operating shaft occupies position #1; and the line switch 60 is closed in response to movement of the operating shaft 51 into its "axial start" position.

The present fourth modified program is fundamentally the same as basic program, except that in each of the four instances in which the spin tub 20 is filled with water, the drive motor 40 is started, in the forward direction after the expiration of a fill time interval of 5 minutes, instead of after the normal fill time interval of 4 minutes. This is accomplished in each instance (in positions #6, #25, #37 and #47 of the operating shaft 51) by operation of the control cam 3B to actuate the switch spring FL to close the switch spring ML. Closure of the switch springs FL, ML connects the conductor 208 directly to the conductor 206, when the manual dial 182 occupies its "large load" position; whereby the forward start and run circuits for respectively energizing the start and run windings 44 and 42 are completed to initiate forward starting of the drive motor 40; with the result that the device 46 is operated to actuate the bridging member 48 to open its back contacts, so as to interrupt the circuits for the hot solenoid 27a, or for both the hot solenoid 27a and the cold solenoid 28a, as previously explained.

Thus in the present fourth modified program the drive motor 40 is started 1 minute late with respect to the basic program, so that the water cut-off occurs late to provide the spin tub 20 with an extra fill of water. Specifically, in the present fourth modified program each water fill time interval is 5 minutes, instead of 4 minutes, as in the basic program.

This present fourth modified program is otherwise the same as the basic program, as previously described.

Consider now the presetting of a fifth modified program, modified with respect to the basic program in the

particular that the second wash is to be omitted. The presetting of this fifth modified program is fundamentally the same as that previously described in conjunction with the presetting of the basic program, except that in this case, in the control switch 110, the tab 111, instead of the tab 112, is depressed; and thereafter the operator manually pulls the control dial 52 outwardly into its "axial start" position. At this time, the operating shaft 51 occupies position #1; and the line switch 60 is closed in response to movement of the operating shaft 51 into its "axial start" position.

The initial portion of this fifth modified program is the same as that of the basic program as previously described; however, when the operating shaft 51 is rotated into position #19, the control cam 5T actuates the switch spring P3 to close the switch spring A3, thereby to complete a tertiary circuit for energizing the position advance motor PA. This tertiary circuit includes the elements L1, 60, 226, P3, A3, 222, 113, 224, PA, 206, 202, 201, L2. The position advance motor PA rotates the operating shaft 51 rapidly from position #19 into position #30. In position #30 of the operating shaft 51, the control cam 5T actuates the switch spring P3 to open the switch spring A3, so as to interrupt the tertiary circuit for the position advance motor PA.

The remainder of the fifth modified program is the same as that of the basic program as previously described; and it will be understood that in the present fifth modified program the second wash is omitted entirely.

Consider now the presetting of a sixth modified program, modified with respect to the basic program in the particular that the bonus rinse (the first rinse) is to be omitted. The presetting of this sixth modified program is fundamentally the same as that previously described in conjunction with the presetting of the basic program, except that in this case, in the control switch 150 the tab 151, instead of the tab 152, is depressed; and thereafter the operator manually pulls the control dial 52 outwardly into its "axial start" position. At this time, the operating shaft 51 occupies position #1; and the line switch 60 is closed in response to movement of the operating shaft 51 into its "axial start" position.

The initial portion of this sixth modified program is the same as that of the basic program as previously described; however, when the operating shaft 51 is rotated into position #31, the control cam 3T actuates the switch spring P4 to close the switch spring A4, thereby to complete a quaternary circuit for energizing the position advance motor PA. This quaternary circuit includes the elements L1, 60, 226, P3, B1, 223, 153, 221, P4, A4, 224, PA, 206, 202, 201, L2. The position advance motor PA rotates the operating shaft 51 rapidly from position #31 into position #41. In position #41 of the operating shaft 51 the control cam 3T actuates the switch spring P4 to open the switch spring A4, so as to interrupt the quaternary circuit for the position advance motor PA.

The remainder of the sixth modified program is the same as that of the basic program as previously described; and it will be understood that in the present sixth modified program the bonus rinse is omitted entirely.

Consider now the presetting of a seventh modified program, modified with respect to the basic program in the particular that warm water, instead of hot water, is desired in the first wash cycle. The presetting of this seventh modified program is fundamentally the same as that previously described in conjunction with the presetting of the basic program, except that in this case, in the control switch 120 the tab 122, instead of the tab 121, is depressed prior to the manual operation of the control dial 52 into its "axial start" position, in the manner previously explained. In this case, the depressed tab 122 in the control switch 120 connects the conductor 204 to the conductor 201 at the switch spring 123, so that in the program, at positions #1 to #5, inclusive, of the operating shaft 51, the operation of the control cam 6B to close the

switch spring MC to the switch spring H effects the energization of the cold solenoid 28a in parallel with the hot solenoid 27a, since at these positions noted, the control cam 7B actuates the switch spring C1 to close the switch spring CW. The energization of the hot solenoid 27a, together with the cold solenoid 28a, effects the introduction of warm water, instead of hot water, into the spin tub 20 via the tube 26 in the two corresponding fill sections of the first wash cycle, in the manner previously explained.

The remainder of the seventh modified program is the same as that of the basic program as previously described; and it will be understood that in the present seventh modified program the spin tub 20 is filled with hot water for the second wash.

Consider now the presetting of an eighth modified program, modified with respect to the basic program in the particular that cold water, instead of warm water, is desired in each of the two rinse cycles. The presetting of this eighth modified program is fundamentally the same as that previously described in conjunction with the presetting of the basic program, except that in this case, in the control switch 160 the tab 162, instead of the tab 161, is depressed prior to the manual operation of the control dial 52 into its "axial start" position, in the manner previously explained. In this case, the depressed tab 162 in the control switch 160 brings about the disconnection of the conductor 204 from the conductor 203, at the switch 163, so that in the program, at positions #32 to #36, inclusive, and #42 to #48, inclusive, of the operating shaft 51, the operation of the control cam 1B to close the switch spring CR to the switch spring C2 effects the energization of only the cold solenoid 28a, notwithstanding the fact that at these positions noted, the control cam 7B actuates the switch spring C1 to close the switch spring HR. The hot solenoid 27a is not energized in parallel with the cold solenoid 28a in the two sets of positions noted, since the conductor 204 is disconnected from the conductor 203 at the switch spring 163 in the control switch 160 by virtue of the depressed pushbutton 161 thereof.

The remainder of the eighth modified program is the same as that of the basic program as previously described; and it will be understood that in the present eighth modified program, the spin tub 20 is filled with cold rinse water for both the bonus rinse and the final rinse.

Consider now the presetting of a ninth modified program, modified with respect to the basic program in the particular that a short quiescent soaking phase of the clothes suspended in the wash water in the spin tub 20 is desired in the intermediate portion of the first wash cycle. The presetting of the ninth modified program is fundamentally the same as that previously described in conjunction with the presetting of the basic program, except that in this case, in the control switch 130 the tab 131, instead of the tab 132, is depressed prior to the manual operation of the control dial 52 into its "axial start" position in the manner previously explained. In this case, the depression tab 131 in the control switch 130 opens the switch spring 133 to disconnect the conductor 218 from the conductor 217 for a purpose more fully explained below. Operation of the timer motor TM is initiated in position #1 of the operating shaft 51; and subsequently, in position #5 of the operating shaft 51 forward rotation of the rotor 44 of the drive motor 40 is initiated in the manner previously explained. Thereafter, when the operating shaft 51 is rotated into position #7, the control cam 1T actuates the switch spring P5 to open the switch spring SS, thereby to disconnect the conductor 218 from the conductor 217; whereby at this time, the conductor 218 is totally disconnected from the conductor 217 by virtue of the open switch spring 133 in the control switch 130, with the result that the previously traced forward holding circuit for the run

winding 42 of the drive motor 40 is interrupted causing the rotor 41 to stop, thereby to arrest the oscillation of the agitator 22 and the consequent first washing action thereof in the spin tub 20 at this time. However, the timer motor TM continues to operate and after a time interval of about 6 minutes, the operating shaft 51 is rotated into position #13, in order to cause the control cam 1T to actuate the switch spring P5 to close the switch spring SS. The closure of the switch springs P5, SS, recomplete the previously traced forward start and run circuits for the start and run windings 44 and 42 of the drive motor 40, with the result that the rotor 41 thereof is again started and rotated in the forward direction, so as again to initiate oscillation of the agitator 22, so as again to effect the first washing action in the spin tub 20. The first washing action continues when thus initiated in position #13 of the operating shaft 51 for a time interval of about 2 minutes, whereupon the operating shaft 51 is rotated into position #15, whereby again the forward holding circuit for the run winding 42 of the drive motor 40 is interrupted as a consequence of the action of the control cam 2B in actuating the switch spring MP to open the switch spring W. The remainder of this ninth modified program is identical to that previously described in conjunction with the basic program and is not repeated in the interest of brevity.

Reviewing this ninth modified program, the wash cycle therein is characterized by a first phase of a time duration of 4 minutes in which hot water is filled into the spin tub 20, by a second phase of a time duration of 2 minutes in which the agitator 22 is oscillated, by a third phase of a time duration of 6 minutes in which the agitator 22 is at rest and the clothes suspended in the wash water in the spin tub 22 are subjected to a corresponding quiescent soaking action, by a fourth phase of a time duration of 2 minutes in which the agitator 22 is oscillated, and by a fifth phase of a short time duration of 3 minutes in which the spin tub 20 is spun in order to expel the wash water from the spin tub 20 and from the clothes contained therein.

Also, in conjunction with the presetting of the ninth modified program, it is noted that the control switch 190 should be set into its "10-minutes" position, when the tab 131 of the control switch 130 occupies its depressed position, so as to insure ample time of 10 minutes in the first wash cycle to carry out the required short quiescent soaking phase of 6 minutes, as described above.

Consider now the presetting of a tenth modified program, modified with respect to the basic program in the particular that the agitator 22 is to be oscillated at its gentle rate of 45 cycles per minute, instead of at its normal rate of 64 cycles per minute, each time oscillation thereof is initiated in the program, and specifically in the first wash cycle, in the second wash cycle, in the bonus rinse cycle and in the final rinse cycle. In this case, in the control switch 140 the tab 142, instead of the tab 141, is depressed prior to the manual operation of the control dial 52 into its "axial start" position. The depressed tab 142 effects closing at the switch spring 144 of the conductor 211 to the conductor 227, and opening at the switch spring 143 of the conductor 211 from the conductor 225.

In this case starting of the drive motor 40, by energization of the 4-pole start winding 44 in the forward direction and energization of the 4-pole run winding 42, is the same in each instance, as previously explained. However, when the centrifugal device 46 is operated at about 60% of the normal running speed of the 4-pole run winding 42, a circuit change is made wherein the 6-pole run winding 43 is substituted for the 4-pole run winding 42, with the result that the rotor 41 runs at a slow speed of about 1140 r.p.m. in the forward direction, so as to cause oscillation of the agitator 122 at its rate of about 45 cycles per minute, and the consequent produc-

tion thereby of a gentle washing action upon the clothes suspended in the water in the spin tub 20.

Specifically, the device 46 actuates the bridging member 49 to open its back contacts, so as to open the conductor 227 from the conductor 215 in order to deenergize the 4-pole start winding 44, and so as to open the conductor 227 from the conductor 225 in order to deenergize the 4-pole run winding 42. Also, the device 46 actuates the bridging member 49 to close its front contacts, so as to close the conductor 227 to the conductor 229 in order to energize the 6-pole run winding 43. The fragmentary portion of the circuit mentioned for energizing the 4-pole run winding 42 includes the elements L1, . . ., 211, 144, 227, 49 and its back contacts, 225, 42, 208, . . ., L2; and the fragmentary portion of the circuit mentioned for energizing the 6-pole run winding 43 includes the elements L1, . . ., 211, 144, 227, 49 and its front contacts, 43, 208, . . ., L2.

This tenth modified program is otherwise the same as the basic program as previously described.

Consider now the presetting of an eleventh modified program, modified with respect to the basic program in the particular that the spin tub 20 is spun at its gentle speed 420 r.p.m., instead of at its normal speed of 640 r.p.m., each time spinning thereof is initiated in the program, and specifically in the first wash cycle, in the second wash cycle, in the bonus rinse cycle and in the final rinse cycle. In this case, in the control switch 170, the tab 172, instead of the tab 171, is depressed prior to the manual operation of the control dial 52 into its "axial start" position. The depressed tab 172 effects closing at the switch spring 174 of the conductor 213 to the conductor 227 and opening at the switch spring 173 of the conductor 213 from the conductor 225.

In this case, starting of the drive motor 40, by energization of the 4-pole start winding 44 in the reverse direction and energization of the 4-pole run winding 42, is the same in each instance, as previously explained. However, when the centrifugal device 46 is operated at about 60% of the normal running speed of the 4-pole run winding 42, a circuit change is made wherein the 6-pole run winding 43 is substituted for the 4-pole run winding 42, with the result that the rotor 41 runs at its slow speed of about 1140 r.p.m. in the reverse direction, so as to cause spinning of the spin tub 20 at its speed of about 420 r.p.m., and the consequent production thereby of a gentle water-extraction action upon the clothes therein.

Specifically, the device 46 actuates the bridging member U49 to open its back contacts, so as to open the conductor 227 from the conductor 215 in order to deenergize the 4-pole start winding 44, and so as to open the conductor 227 from the conductor 225 in order to deenergize the 4-pole run winding 42. Also, the device 46 actuates the bridging member 49 to close its front contacts, so as to close the conductor 227 to the conductor 229 in order to energize the 6-pole run winding 44. The fragmentary portion of the circuit mentioned for energizing the 4-pole run winding 42 includes the elements L1, . . ., 213, 174, 227, 49 and its back contacts 225, 42, 208, . . ., L2; and the fragmentary portion of the circuit mentioned for energizing the 6-pole run winding 43 includes the elements L1, . . ., 213, 174, 227, 49 and its front contacts, 43, 208, . . ., L2.

This eleventh modified program is otherwise the same as the basic program, as previously described.

By way of review, it is noted that the first wash cycle may be carried out employing either hot water or warm water depending upon the positions of the pushbuttons 121 and 122 of the control switch 120. On the other hand, if the second wash cycle is included in a program, as established by operation of the pushbutton 112 of the control switch 110, it is always carried out employing hot water. The bonus rinse cycle may be selectively included or excluded with respect to a program, as determined by operations of the pushbuttons 152 and 151 of 75

the control switch 150, but if it is included, it is always carried out with water having the same temperature as that preselected for the final rinse cycle, as established by the positions of the tabs 161 and 162 of the control switch 160, which water may be warm or cold, as previously explained.

In view of the foregoing explanation of the presetting of the basic program and the presetting of the eleven individual modified programs, it will be understood that two or more of the modified programs may be preset simultaneously, when such modified programs are not mutually inconsistent with each other. However, there is never any conflict in the setting of the modified programs mentioned by virtue of the interlocks incorporated in the various ones of the control switches 110, 120, 130, 140, 150, 160 and 170 of the rocker type, and by virtue of the fact that the control switches 180 and 190 are of the rotary type.

The connection and arrangement of the control circuit, as well as the mode of operation thereof, as described above, form no part of the present invention and are disclosed and claimed in the copending application of Frank D. Low, Serial No. 330,101, filed December 12, 1963.

Further considering the construction and arrangement of the control console 100, embodying the features of the present invention, reference is made to FIGS. 8 to 14, inclusive; wherein it will be observed that the glass tube 301, which is of clear or transparent material, is mounted for rotation behind the front plate 101 upon a rear plate 310 by a pair of spaced-apart brackets 311 and 312; whereby the tube 301 is thus rotatable with respect to the actuators 110R, 120R, etc., that are rockably mounted thereupon in side-by-side relation with each other, as previously noted. The actuators 110R, 120R, etc., are of identical construction, and each thereof is preferably integrally molded of a clear or transparent material, such as an acrylic resin, polymethyl methacrylate being quite satisfactory for the present purpose. As best shown in FIGS. 9, 10 and 11, the actuator 110R comprises the central barrel section 116 having the cylindrical opening 116a therethrough accommodating the mounting thereof upon the tube 301 with a nice fit therebetween, so as to permit the previously mentioned rocking of the actuator 110R with respect to the exterior surface of the tube 301. The top and bottom portions of the barrel 116 respectively carry the two radially outwardly projecting wing-like tabs 111 and 112 that are arranged with an included angle therebetween that is somewhat less than 180°, such, for example, as 160°. The rear side of the barrel 116 carries an arm 117 projecting radially rearwardly therefrom and cooperating with the associated unitary switch 110. For example, as illustrated, a slot 117a is formed in the extreme rear end of the arm 117 that receives an operating bar 110a carried by the operating arm 110b of the switch 110.

Thus, when the tab 111 is depressed, the same is rocked rearwardly substantially into the plane of the front wall 101 and the tab 112 is rocked forwardly with respect to the plane of the front wall 101, as shown in FIG. 10. On the other hand, when the tab 112 is depressed, the same is rocked rearwardly substantially into the plane of the front wall 101 and the tab 111 is rocked forwardly with respect to the plane of the front wall 101, as shown in FIG. 11. Depression of the tab 111 actuates the switch 110 into one of its two positions; and depression of the tab 112 actuates the switch 110 into the other of its two positions. These actuations are effected through the cooperation of the slot 117a formed in the arm 117 and the bar 110a carried by the switch arm 110b, in an obvious manner; and the switch 110 snaps between its two switch positions, since it is of the snap-acting type.

The rear surfaces of the tabs 111 and 112 respective-

ly carry a plurality of groups of serrations 111a and 112a that respectively comprise lenses in two optical systems that also includes an elongated longitudinally extending fluorescent lamp 313 disposed substantially along the longitudinally extending central axis of the tube 301; the lamp 313 being removably secured in place in two sockets 314 and 315 respectively carried by the two brackets 311 and 312.

As shown in FIG. 3, the lamp 313 is of conventional construction and is provided with a conventional ballast circuit 316 for starting and operating the same. The ballast circuit 316 is supplied with power between the line L1 and the conductor 206; and the supply circuit includes a lamp switch 317 of any suitable type, that may be carried by the front wall 101 and provided with a manually operable button 318 positioned below the window 106, as shown in FIG. 8. Of course, closure of the lamp switch 317 causes the ballast circuit 316 to illuminate the lamp 313 in a conventional manner.

Referring now to FIG. 14, the index sheet 303 there illustrated may be formed of any suitable flexible film, such as cellophane, a synthetic organic resin, etc., that is capable of carrying printing in a ready manner. Specifically, the index sheet 303 is formed of clear or transparent material, and the background thereof carries a black printed mask rendering the same substantially opaque. On the left-hand side of the index sheet 303 the indices "Wool," "Delicate Wash'n Wear," "Sturdy Wash'n Wear," "Extra Heavy Soil," "Heavy Soil," "Bright Colors," "Colorfast" and "Babyclothes" are printed, these indices or legends being arranged in a vertical tier or column, as illustrated. In the arrangement: the legends "Wool," "Extra Heavy Soil," "Heavy Soil," and "Babyclothes" are printed in red ink to key those items to the "10-minute" position of the dial 192 of the time control switch 190 that is also provided with a red background, as previously noted. Similarly: the legends "Sturdy Wash'n Wear," "Bright Colors" and "Colorfast" are printed in yellow ink to key these items to the "7-minutes" position of the dial 192; and the legend "Delicate Wash'n Wear" is printed in blue ink to key this item to the "4-minutes" position of the dial 192. On the central portion and on the right-hand side of the index sheet 303, there are arranged seven vertical tiers of windows positioned in longitudinally spaced-apart relation and respectively corresponding to the actuating members 110R, 120R, 130R, 140R, 150R, 160R and 170R. Each of the tiers of windows comprises a number of groups of windows; and each of the groups of windows comprises at least one pair of windows; and each of the pairs of windows comprising an individual clear or transparent window 303c and an individual red window 303r, the red window being produced by printing in red ink. The groups of windows are arranged in coordinate positions disposed above and below the center line of the index sheet, indicated at 303', as explained more fully hereinafter.

The index sheet 303 is arranged interiorly of the glass tube 301, as best shown in FIGS. 10, 11 and 13, and suitably secured in place upon the interior surface of the tube 301, as by a transparent adhesive; and in the arrangement, the legends "Babyclothes," etc., are disposed below and in alignment with the window 106 formed in the front wall 101, as shown in FIG. 8. Also, the seven tiers of windows 303c, 303r are respectively disposed directly below the corresponding actuating members 110R, 120R, etc., as best shown in FIGS. 9, 10, 11 and 13.

Again referring to FIGS. 8, 9 and 12, it will be appreciated that the tube 301 has seven rotary positions in which the seven legends "Babyclothes," etc., are respectively presented in the window 106 formed in the front wall 101. Also, it will be observed that when the tube 301 occupies any given one of its rotary positions mentioned, coordinate pairs of the windows 303c, 303r are

65

presented to one or the other of the two tabs carried by each of the seven actuating members 110R, 120R, etc., the coordinate plan being explained subsequently. For example, when the tube 301 occupies the one of its seven rotary positions in which the legend "Babyclothes" appears in the window 105, a pair of the windows 303c, 303r is presented to the tab 111 carried by the actuating member 110R, as shown in FIGS. 9, 10 and 11; and specifically, the clear window 303c is positioned slightly to the left of top vertical and the red window 303r is positioned substantially at top vertical, as best shown in FIGS. 10 and 11. Now assume that the lamp 313 is illuminated, so that the interior of the tube 301 is illuminated; whereby a beam of white light, indicated at 313w, passes through the clear window 303c, and a beam of red light, indicated at 313r, passes through the red window 303r. First assume that at this time the tab 111 is depressed, as shown in FIG. 10, this positioning of the tab 111 causes the red light beam 313r to impinge upon the serrations 111a, whereby the same is refracted forwardly toward an observer, so that the front face of the tab 111 glows red to the observer. Also, in this position of the tab 111 the white light beam 313w passes upwardly through the tab 111 and forwardly of the serrations 111a, whereby the observer obtains no particular impression thereof, and simply observes the bright red refracted light beam, as indicated at 313rr in FIG. 10. Now assume that at this time the tab 112 is depressed, as shown in FIG. 11, this positioning of the tab 111 causes the white light beam 313w to impinge upon the serrations 111a, whereby the same is refracted forwardly toward an observer, so that the front face of the tab 111 glows white to the observer. Also, in this position of the tab 111 the red light beam 313r passes upwardly rearwardly of the serrations 111a, whereby the observer obtains no particular impression thereof, and simply observes the bright white refracted light beam, as indicated at 313ww in FIG. 11. Thus, when the tube 301 occupies its rotary position presenting the legend "Babyclothes" in the window 106, the lamp 313 causes the front face of the tab 111 to glow either red (FIG. 10) or white (FIG. 11) depending upon the depressed position of the tab 111 (FIG. 10) or the depressed position of the tab 112 (FIG. 11).

At this point it is noted that, likewise, one or the other of each of the pairs of tabs 121, 122 and 131, 132, etc., glows either red or white, at this time, depending upon the position of the corresponding actuating member 130R, 140R, etc. Before explaining the coordination of the windows 303c, 303w, it is simply mentioned that each of the tabs that glows white is in a recommended position, and that each of the tabs that glows red is in a non-recommended position with respect to the recommended program in the machine 10 for processing baby clothes. Of course, any tab glowing red may be made to glow white merely by depressing the same, as explained above in conjunction with FIGS. 10 and 11.

Turning now to FIG. 15, in this chart there are set forth the manufacturer's recommendations of seven clothes processing programs to be employed in the clothes washing machine 10 for respectively processing the seven common types of fabrics previously mentioned. For example, the recommended processing program for baby clothes includes a first wash cycle of a time duration of ten minutes in warm water and including a soak period, a second wash cycle in hot water, a bonus rinse in cold water, a final rinse in cold water, a normal agitator speed and a normal spin speed.

Turning now to FIG. 16, in this chart there are set forth the seven combinations of the tabs of the control switches carried by the control console 100 that must be operated in order to preset the respective seven recommended clothes processing programs into the control circuit of the machine 10 and that respective corresponding to the seven common types of fabrics previously mentioned. For example, the combination of the tabs of the

control switches that must be operated in order to preset the recommended processing program for baby clothes comprises the individual tabs 112, 122, 131, 141, 152, 162 and 171. Also, the dial 192 of the time control switch 190 must be set into its "10-minutes" position. Further, the dial 182 of the fill control switch 180 should be set into its particular position corresponding to the load of baby clothes that is to be processed in the machine 10.

Now assuming that a large load of baby clothes is to be washed in the machine 10, the operator sets the dial 182 of the fill control switch into its corresponding "Large Load" position, and then rotates the wheel 302 carried by the tube 301 to expose the legend "Babyclothes" in the window 106 in the front wall 101. Of course, the load of baby clothes is placed into the tub 20, together with the required detergent to be employed in the first wash cycle. Also, it may be assumed that the lamp switch 317 is closed at this time, and that the dial 52 of the program controller 50 occupies its "rotary start" position and its "axial stop" position. The lamp 313 is illuminated to effect illumination of the legend "Babyclothes" in the window 106; which legend "Babyclothes" is in red so as to key the recommended processing program to the corresponding red or "10-minutes" position of the dial 192 of the time control switch 190. Thus, it may be assumed that the dial 192 occupies its "10-minutes" position, and if not, the operator will rotate the dial 192 into its "10-minutes" position, so as to match the red color key of the dial 192 to the red color key of the illuminated legend "Babyclothes" appearing in the window 106.

At this time, the illumination of the corresponding group of tabs 112, 122, 131, 141, 152, 162 and 171 may be entirely at random depending upon the prior use of the machine 10; whereby some of the tabs in this group glow white and other of the tabs in this group glow red. Each tab 112, etc., that glows white is in a position conforming to the recommended position of the associated control switch 110, etc., and each tab 112, etc., that glows red is in a position nonconforming to the recommended position of the associated control switch 110, etc. Also, each tab 112, etc., that glows red is in an out position with respect to the front wall 101; whereby the operator may change the color of any tab glowing red merely by depressing the same, as previously explained.

Accordingly, the operator may conform the preselected and preset processing program to that recommended by the tube 301 in its particular rotary position "Babyclothes" merely by depressing each of the tabs 112, etc., that glows red; whereby each of the tabs 112, etc., then glows white indicating to the operator that all of the control switches 110 to 170, inclusive, occupy the recommended positions for presetting the recommended processing program for baby clothes. When the manual dial 52 is subsequently moved to its "axial start" position, the program controller 50 operates to carry out the preset program in the machine 10.

Reviewing the cooperation of the tube 301 with the actuating members 110R, 120R, etc., it is emphasized that this arrangement merely prompts or advises the operator with respect to whether the preset program conforms or nonconforms to the recommended program for baby clothes; whereby this apparatus performs no directing or compelling function with respect to the preselecting of the program that the operator may employ in the program that is actually carried out in the machine 10 incident to operation of the program controller 50. However, this apparatus advises the operator with respect to whether each of the seven control switches 110 to 170, inclusive, occupies a position conforming to the recommended position thereof in the recommended program for processing baby clothes.

Referring now to FIGS. 12 and 14, the coordination of the windows 303c, 303r in the index sheet 303 and the

positions of the actuating members 110R, 120R, etc. will now be explained, when the tube 301 occupies its rotary position causing the legend "Babyclothes" carried by the index sheet 303 arranged within the tube 301 to be illuminated by the lamp 313 in the window 106 in the front wall 101. Specifically, in this position of the tube 301: the black background of the index sheet 303 is located below the tab 111 regardless of the position of the actuating member 110R, whereby the tab 111 is not illuminated; the red window 303r is located below the tab 112, if the tab 111 is depressed, whereby the tab 112 glows red; and the clear window 303c is located below the tab 112, if the tab 112 is depressed, whereby the tab 112 glows white. Accordingly, the recommended program for baby clothes includes the control switch 110 in its switch position obtained by the depressed position of the tab 112 carried by the actuating member 110R; whereby the depressed tab 112 glows white indicating the conformity noted. On the other hand, if the control switch 110 is in the opposite switch position produced by the depressed tab 111 carried by the actuating member 110R, then the tab 112 is positioned out with respect to the front wall 101 and glows red indicating the nonconformity noted.

Also, in this position of the tube 301, the black background of the index sheet 303 is located below the tabs 121, 132, 142, 151, 161 and 172, whereby these tabs are also not illuminated. On the other hand, in this position of the tube 301, individual pairs of the red-clear windows 303r, 303c are also operatively associated with the tabs 122, 131, 141, 152, 162 and 171. Specifically, clear windows 303c in the index sheet 303 are respectively located below depressed ones of the tabs 122, 131, 141, 152, 162 and 171, causing each of these depressed tabs to glow white; while red windows 303r in the index sheet 303 are respectively located below non-depressed ones of the tabs 122, 131, 141, 152, 162 and 171, causing each of these non-depressed tabs to glow red. Of course, the statement that the tab 122 is "non-depressed" merely means that the companion tab 121 is depressed, since the common actuating member 120R comprises a rocker so that one of the tabs 121, 122 is depressed and the other of the tabs 121, 122 is not depressed or is "non-depressed."

Again examining the index sheet 303, it will be observed that the first horizontal row of black backgrounds and pairs of windows 303c, 303r is positioned above the center line 303' of the index sheet 303 is located below the tabs 111, 121, 131, 141, 151, 161 and 171, when the tube 301 occupies its rotary position "Babyclothes"; and, also, the last horizontal row of black backgrounds and pairs of windows 303c, 303r positioned below the center line 303' of the index sheet 303 is located below the tabs 112, 122, 132, 142, 152, 162 and 172, when the tube 301 occupies its rotary position "Babyclothes." In the pairs of windows 303r, 303c located above the center line 303' of the index sheet 303, the red windows 303r are positioned toward the center line 303' and the clear windows 303c are positioned away from the center line 303'. Similarly, in the pairs of windows 303r, 303c located below the center line 303' of the index sheet 303, the red windows 303r are positioned toward the center line 303' and the clear windows 303c are positioned away from the center line 303'.

The other of the pairs of windows 303r, 303c, in the seven upper vertical tiers and in the seven lower vertical tiers, and in the seven upper horizontal rows and in the seven lower horizontal rows, are coordinated in a similar manner for the other rotary positions "Colorfast," "Bright Colors," etc., of the tube 301; whereby the tube 301 in its seven rotary positions respectively corresponding to the seven common fabrics noted transmits the red and white light beams to proper ones of the seven pairs of tabs 111, 112 and 121, 122, etc., thereby to indicate to the operator the conformity and nonconformity of the positions of the actuating members 110R, 120R, etc., with respect to the recommended positions thereof to carry out

the seven corresponding recommended programs in the machine 10. Again it is noted that this apparatus, including the tube 301 carrying the index sheet 303, serves entirely, an advisory or prompting function, as contrasted with an enforcing function, with respect to the preselecting or presetting of the programs into the control circuit of the machine 10. Thus, the operator exercises the actual presetting function and is free to conform or overrule the advice of the prompting apparatus.

In view of the foregoing it is apparent that there has been provided a control console comprising an elongated tube, a number of manually operable actuating members mounted in side-by-side relation upon the tube for independent rocking movements with respect thereto, a number of switches each of the snap-acting two-position type, a number of operative connections respectively between the actuating members and the switches, each one of the actuating members having two positions and being selectively rockable therebetween upon the tube to actuate between its two positions the corresponding one of the switches, an elongated lamp arranged in the tube, and a visual signalling system including windows provided in the tube and cooperating with the actuating members for selectively indicating to an observer the operated positions of the actuating members. Also, there has been provided in an appliance a control console for selectively presetting a variable cyclic processing program into a control circuit for the appliance and for selectively indicating to an operator of the appliance a number of recommended programs for a corresponding number of different types of materials that may be processed in the appliance and for indicating the points of conformity and the points of nonconformity between a preset program and a recommended program. Further, there has been provided an automatic clothes washing machine incorporating a control console of the character noted, wherein the control console not only accommodates the ready presetting of a variable processing program, into the machine, but it also produces an indication of a number of recommended programs for a corresponding number of common types of fabrics, and further indicates to the operator of the machine the points of conformity and the points of nonconformity between a preset program and a recommended program.

While there has been described what is at present considered to be the preferred embodiment of the invention, it will be understood that various modifications may be made therein, and it is intended to cover in the appended claims all such modifications as fall within the true spirit and scope of the invention.

What is claimed is:

1. In an automatic clothes washing machine including a tub adapted to receive clothes to be processed, and mechanism selectively operative to subject the clothes in said tub to a clothes processing program composed of a set of fixed clothes processing components and a group of variable clothes processing components; the combination comprising a group of manually settable devices respectively corresponding to said variable components, each of said devices having a plurality of positions respectively corresponding to predetermined characteristics of the corresponding variable component, each of said devices being operative into any one of its positions to preselect the corresponding one of the characteristics of the corresponding variable component, a manually settable selector having a plurality of settings respectively corresponding to different types of fabrics that may be processed in said machine, each setting of said selector also corresponding to recommended individual positions of said devices, a group of visual signals respectively operatively associated with said devices, means governed jointly by the position of said selector and by the positions of said devices for selectively operating said signals to present a visual indication of the ones of said devices that occupy individual positions conforming to those

recommended by said selector in its particular position and of the others of said devices that occupy individual positions nonconforming to those recommended by said selector in its particular position, a program controller operative through a cycle, means controlled by operation of said program controller through its cycle for selectively operating said mechanism to produce said program in said machine and including said fixed components and the preselected characteristics of said variable components, and manually operable means for initiating operation of said program controller.

2. The automatic clothes washing machine combination set forth in claim 1, wherein said group of variable clothes processing components includes the temperature of the water employed in the wash cycle and characterized by being either hot or warm, and the one of said devices corresponding to the temperature of the wash water has hot and warm positions respectively corresponding to these two characteristics thereof.

3. The automatic clothes washing machine combination set forth in claim 1, where said group of variable clothes processing components includes the temperature of the water employed in the rinse cycle and characterized by being either warm or cold, and the one of said devices corresponding to the temperature of the rinse water has warm and cold positions respectively corresponding to these two characteristics thereof.

4. The automatic clothes washing machine combination set forth in claim 1, wherein said group of variable clothes processing components includes the mode of the agitation of the clothes in the wash water in the wash cycle and in the rinse water in the rinse cycle and characterized by being either normal or gentle, and the one of said devices corresponding to the mode of agitation has normal and gentle positions respectively corresponding to these two characteristics thereof.

5. The automatic clothes washing machine combination set forth in claim 1, where said group of variable clothes processing components includes the mode of extraction of the wash water at the conclusion of the wash cycle and of the rinse water at the conclusion of the rinse cycle, and the one of said devices corresponding to the mode of extraction has normal and gentle positions respectively corresponding to these two characteristics thereof.

6. The automatic clothes washing machine combination set forth in claim 1, wherein said group of variable components includes the mode of application of the agitation of the clothes in the wash water in the wash cycle and characterized by being either continuous or intermittent with a quiescent soak period between the two portions thereof, and the one of said devices corresponding to the mode of application of the agitation has continuous and intermittent positions respectively corresponding to these two characteristics thereof.

7. In an automatic clothes washing machine including a tub adapted to receive clothes to be processed, and mechanism selectively operative to subject the clothes in said tub to a clothes processing program composed of a set of required clothes processing components and one or more preselected ones of a group of elective clothes processing components; the combination comprising a group of manually settable devices respectively corresponding to said elective components, each of said devices having include and exclude positions and being selectively operative into its respective positions corresponding to preselect the inclusion and the exclusion of the corresponding elective component with respect to said program, a manually settable selector having a plurality of settings respectively corresponding to different types of fabrics that may be processed in said machine, each setting of said selector also corresponding to recommended individual positions of said devices, a group of visual signals respectively operatively associated with said devices, means governed jointly by the position of said selector and by the positions of said devices for selectively operating said signals to present a visual indication of the ones of said devices that occupy individual positions conforming to those

and by the positions of said devices for selectively operating said signals to present a visual indication of the ones of said devices that occupy individual positions conforming to those recommended by said selector in its particular position and of the others of said devices that occupy individual positions nonconforming to those recommended by said selector in its particular position, a program controller operative through a cycle, means controlled by operation of said program controller through its cycle for selectively operating said mechanism to produce said program in said machine and including said set of required components and the one or more preselected for inclusion of said elective components, and manually operable means for initiating operation of said program controller.

8. The automatic clothes washing machine combination set forth in claim 7, wherein said group of required clothes processing components includes one wash cycle, and said group of elective clothes processing components includes another wash cycle.

9. The automatic clothes washing machine combination set forth in claim 7, wherein said group of required clothes processing components includes one rinse cycle, and said group of elective clothes processing components includes another rinse cycle.

10. In an automatic clothes washing machine including a tub adapted to receive clothes to be processed, and mechanism selectively operative to subject the clothes in said tub to a clothes processing program composed of a group of variable required clothes processing components and a one or more fixed elective clothes processing components; the combination comprising a group of first manually settable devices respectively corresponding to said variable components, each of said first devices having a plurality of positions respectively corresponding to predetermined characteristics of the corresponding variable component, each of said first devices being operative into any one of its positions to preselect the corresponding one of the characteristics of the corresponding variable component, a group of manually settable second devices respectively corresponding to said elective components, each of said second devices having include and exclude positions and being selectively operative into its respective positions correspondingly to preselect the inclusion and the exclusion of the corresponding elective component with respect to said program, a manually settable selector having a plurality of settings respectively corresponding to different types of fabrics that may be processed in said machine, each setting of said selector corresponding to a group of recommended positions of said first and second devices, a group of visual signals respectively operatively associated with said first and second devices, means governed jointly by the position of said selector and by the positions of said first and second devices for selectively operating said signals to present a visual indication of the ones of said first and second devices that occupy individual positions conforming to those recommended by said selector in its particular setting and the others of said first and second devices that occupy individual positions nonconforming to those recommended by said selector in its particular setting, a program controller operative through a cycle, means controlled by operation of said program controller through its cycle for selectively operating said mechanism to produce said program in said machine and including the preselected characteristics of said variable required components and the one or more preselected for inclusion of said fixed elective components, and manually operable means for initiating operation of said program controller.

11. In an automatic clothes washing machine including a tub adapted to receive clothes to be processed, and mechanism selectively operative to subject the clothes in said tub to a clothes processing program including a number of clothes processing components preselected from a corresponding number of matched pairs of clothes process-

ing components; the combination comprising a number of manually settable devices respectively corresponding to said pairs of components, each of said devices having two positions respectively corresponding to the individual components of the corresponding pair of components, each of said devices being operative into either one of its positions to preselect the corresponding one of the corresponding pair of components, a manually settable selector having a plurality of positions respectively corresponding to different types of fabrics that may be processed in said machine, each position of said selector also corresponding to recommended individual positions of said devices, a number of visual signals respectively operatively associated with said devices, means governed jointly by the position of said selector and by the positions of said devices for selectively operating said signals to present a visual indication of the ones of said devices that occupy individual positions conforming to those recommended by said selector in its particular position and of the others of said devices that occupy individual positions nonconforming to those recommended by said selector in its particular position, means controlled by operation of said program controller through its cycle for selectively operating said mechanism to produce said program in said machine and including said number of preselected components, and manually operable means for initiating operation of said program controller.

12. The automatic clothes washing machine combination set forth in claim 11, wherein said signal operating means operates in first manner said ones of said signals respectively corresponding to said ones of said devices that occupy said individual conforming positions and operates in a second manner said others of said signals respectively corresponding to said others of said devices that occupy said individual nonconforming positions.

13. The automatic clothes washing machine combination set forth in claim 11, wherein said signal operating means operates in accordance with a first color key said ones of said signals respectively corresponding to said devices that occupy said individual conforming positions and operates in accordance with a second color key said others of said signals respectively corresponding to said others of said devices that occupy said individual nonconforming positions.

14. In an automatic clothes washing machine including a tub adapted to receive clothes to be processed, and mechanism selectively operative to subject the clothes in said tub to a clothes processing program including a number of clothes processing components preselected from a corresponding number of matched pairs of clothes processing components; the combination comprising a number of switches respectively corresponding to said pairs of components, each of said switches having two positions respectively corresponding to the individual components of the corresponding pair of components, each of said switches being operative into either one of its positions to preselect the corresponding one of the corresponding pair of components, each of said switches being of the snap-acting type including a manually operable actuating member having two positions respectively corresponding to the two switch positions thereof, a manually settable selector having a plurality of positions respectively corresponding to different types of fabrics that may be processed in said machine, each position of said selector also corresponding to recommended individual switch positions of said switches, a transmitter governed jointly by the position of said selector and by the positions of said actuating members for transmitting first visual signals to the ones of said actuating members that occupy individual positions conforming to those switch positions recommended by said selector in its particular position and for transmitting second visual signals to the others of said actuating members that occupy individual positions nonconforming to those switch positions recommended by said selector in its particular position, means including

a program controller operative through a cycle for selectively operating said mechanism to produce said program in said machine and including said number of preselected components, and manually operable means for initiating operation of said program controller.

15. The automatic clothes washing machine combination set forth in claim 14, wherein said transmitter essentially comprises an optical system for transmitting said first visual signals in the form of beams of light of a first color to said ones of said actuating members and for transmitting said second visual signals in the form of beams of light of a second color to said others of said actuating members.

16. In an appliance including mechanism selectively operative to carry out a processing program therein and including a number of processing components preselected from a corresponding number of matched pairs of processing components, a number of switches respectively corresponding to said pairs of components, each of said switches having two positions respectively corresponding to the individual components of the corresponding pair of components, each of said switches being of the snap-acting type and operative into either one of its positions to preselect the corresponding one of the corresponding pair of components, and means including a program controller operating through a cycle for selectively operating said mechanism to produce said program in said appliance and including said number of preselected components; a control console comprising an elongated tube mounted for rotation about its longitudinal axis, a number of manually operable actuating members respectively corresponding to said switches and mounted in side-by-side relation upon said tube for independent rocking movements with respect thereto, means respectively interconnecting said actuating members and said switches, each one of said actuating members having two positions and being selectively rockable therebetween upon said tube to actuate between its two switch positions the corresponding one of said switches, said tube having a plurality of rotary positions respectively corresponding to different types of materials that may be processed in said appliance, each rotary position of said tube also corresponding to recommended individual switch positions of said switches, manually operable means for selectively rotating said tube into its different rotary positions, a transmitter governed jointly by the rotary position of said tube and by the positions of said actuating members for transmitting first visual signals to the ones of said actuating members that occupy individual positions conforming to those switch positions recommended by said tube in its particular rotary position and for transmitting second visual signals to the others of said actuating members that occupy individual positions nonconforming to those switch positions recommended by said tube in its particular rotary position, and a manually operable device for initiating operation of said program controller.

17. In an appliance including mechanism selectively operative to carry out a processing program therein and including a number of processing components preselected from a corresponding number of matched pairs of processing components, a number of switches respectively corresponding to said pairs of components, each of said switches having two positions respectively corresponding to the individual components of the corresponding pair of components, each of said switches being of the snap-acting type and operative into either one of its positions to preselect the corresponding one of the corresponding pair of components, and means including a program controller operative through a cycle for selectively operating said mechanism to produce said program in said appliance and including said number of preselected components; a control console comprising an elongated tube mounted for rotation about its longitudinal axis, a number of manually operable actuating members respectively corresponding to said switches and mounted in side-by-side

relation upon said tube for independent rocking movements with respect thereto, means respectively interconnecting said actuating members and said switches, each one of which actuating members having two positions and being selectively rockable therebetween upon said tube to actuate between its two switch positions the corresponding one of said switches, said tube having a plurality of rotary positions respectively corresponding to different types of materials that may be processed in said appliance, each rotary position of said tube also corresponding to recommended individual switch positions of said switches, manually operable means for selectively rotating said tube into its different rotary positions, an elongated lamp mounted within said tube, an optical system governed jointly by the rotary position of said tube and by the positions of said actuating members for transmitting first visual signals from said lamp to the ones of said actuating members that occupy individual positions conforming to those switch positions recommended by said tube in its particular rotary position and for transmitting second visual signals from said lamp to the others of said actuating members that occupy positions nonconforming to those switch positions recommended by said tube in its particular rotary position, and a manually operable device for initiating operation of said program controller.

18. In an appliance including mechanism selectively operative to carry out a processing program therein and including a number of processing components preselected from a corresponding number of matched pairs of processing components, a number of switches respectively corresponding to said pairs of components, each of said switches having two positions respectively corresponding to the individual components of the corresponding pair of components, each of said switches being of the snap-acting type and operative into either one of its positions to preselect the corresponding one of the corresponding pair of components, and means including a program controller operative through a cycle for selectively operating said mechanism to produce said program in said appliance and including said number of preselected components; a control console comprising an elongated tube mounted for rotation about its longitudinal axis, a number of manually operable actuating members respectively corresponding to said switches and mounted in side-by-side relation upon said tube for independent rocking movements with respect thereto, means respectively interconnecting said actuating members and said switches, each one of said actuating members having two positions and being selectively rockable therebetween upon said tube to actuate between its two switch positions the corresponding one of said switches, said tube being provided with a number of groups of windows therein and arranged in side-by-side relation and respectively positioned below the corresponding ones of said actuating members, the individual windows in each of said groups being disposed in circumferentially spaced-apart relation, an elongated lamp mounted within said tube, each of said actuating members being formed of material characterized by the passage of light therethrough, said tube having a plurality of rotary positions respectively corresponding to different types of materials that may be processed in said appliance, each rotary position of said tube also corresponding to recommended individual switch positions of said switches, manually operable means for selectively rotating said tube into its different rotary positions, whereby the individual ones of the windows in said groups that are respectively presented to said actuating members are governed jointly by the circumferential disposition of the windows in each of said groups and by rotary position of said tube and by the positions of said actuating members and are so correlated that first light beams are transmitted from said lamp into the ones of said actuating members that occupy individual positions conforming to those switch positions recommended by

said tube in its particular rotary position and that second light beams are transmitted from said lamp into the others of said actuating members that occupy individual positions nonconforming to those switch positions recommended by said tube in its particular rotary position, and a manually operable device for initiating operation of said program controller.

19. The appliance control console set forth in claim 18, and further comprising a number of groups of panes respectively operatively associated with said groups of windows, each of said groups of panes including a first subgroup of panes of a first color and a second subgroup of panes of a second color, wherein the individual panes in said subgroups in said groups of panes are so correlated that said first light beams transmitted into said ones of said actuating members have said corresponding first color and said second light beams transmitted into said others of said actuating members have said corresponding second color.

20. The appliance control console set forth in claim 18, and further comprising a number of lens structures respectively carried by said actuating members for respectively projecting toward an observer the light beams respectively transmitted into said actuating members.

21. A control console comprising an elongated tube, a number of manually operable actuating members mounted in side-by-side relation upon said tube for independent rocking movements with respect thereto, a number of switches each of the snap-acting two-position type, a number of operative connections respectively between said actuating members and said switches, each one of said actuating members having two positions and being selectively rockable therebetween upon said tube to actuate between its two switch positions the corresponding one of said switches, said tube being provided with a number of pairs of windows therein and arranged in side-by-side relation and respectively positioned below the corresponding ones of said actuating members, the two windows in each of said pairs being disposed in circumferentially spaced-apart relation, a number of pairs of panes respectively operatively associated with said groups of windows, each of said pairs of panes including a first pane of a first color and a second pane of a second color, the two panes in each one of said pairs being so correlated that they are respectively presented to the associated one of said actuating members when it occupies the respective ones of its two positions, and an elongated lamp arranged in said tube, whereby first and second light beams of corresponding first and second colors are selectively transmitted from said lamp into each of said actuating members in accordance with the position thereof.

50

22. The control console set forth in claim 21, wherein each of said actuating members is formed of material characterized by the passage of light therethrough, and further comprising a number of lens structures respectively carried by said actuating members for respectively projecting toward an observer the light beams respectively transmitted into said actuating members.

23. A control console comprising an elongated tube mounted for rotation about its longitudinal axis, said tube having a plurality of predetermined rotary positions, manually operable means for selectively rotating said tube into its different rotary positions, a number of manually operable actuating members mounted in side-by-side relation upon said tube for independent rocking movements with respect thereto, a number of switches each of the snap-acting two-position type, a number of operative connections respectively between said actuating members and said switches, each one of said actuating members having two positions and being selectively rockable therebetween upon said tube to actuate between its two switch positions the corresponding one of said switches, said tube being provided with a number of groups of windows therein and arranged in side-by-side relation and respectively positioned below the corresponding ones of said actuating members, the individual windows in each of said groups being disposed in circumferentially spaced-apart relation, each of said groups of windows including a pair of individual windows for each position of said tube, the individual windows in each one of said groups being so correlated that when said tube occupies any one of its rotary positions and said one actuating member occupies either one of its two positions a corresponding one of the windows in said one group is presented to said one actuating member, and an elongated lamp mounted within said tube for transmitting a number of light beams from said lamp into said actuating members through individual ones of the windows in said groups and depending both upon the particular rotary position of said tube and the particular positions of said actuating members.
